UNITED STATES PATENT OFFICE

1,922,701

TELEPHONE SYSTEM

Herbert M. Friendly, Portland, Oreg.; Milton S. Friendly and Central Republic Bank and Trust Company executors of said Herbert M. Friendly, deceased

Application May 21, 1917. Serial No. 171,637

182 Claims. (Cl. 179—16)

My invention relates to what are generally known as full automatic telephone systems, semi-automatic telephone systems and variations of such systems, including manual telephone systems.

A part of this application has been divided out, forming my pending application Serial No. 362,321, filed March 1, 1920.

An object of my invention is to render more flexible and effective the involved equipments and to enable both central office and outside construction to be conserved to a greater degree than practicable using methods and devices heretofore in practice or known as far as I am aware. Other objects of my invention and the invention itself will be clear from the following description thereof:

In the accompanying drawings:—

Fig. 1 is a holding circuit.

Fig. 2 is a telephone circuit.

Fig. 3 is a well known type of primary line-switch.

Fig. 4 is a well known type of secondary line-switch.

Fig. 5 is an operator's receiving circuit.

Fig. 6 is a first selector.

Fig. 6A is a modified detail of relay D as used in Fig. 6.

Fig. 6B is a registering mechanism as used in connection with Fig. 6.

Fig. 7 is a first selector having two normal levels.

Fig. 8 is a first-second selector having one normal level.

Fig. 9 is a first-second selector having two normal levels.

Fig. 10 is a first-second selector with divided levels.

Fig. 11 is a first-third selector.

Fig. 12 is a first selector with 20-point levels.

Fig. 13 is a double-second selector.

Fig. 14 is a first-second selector.

Fig. 15 is a second-third selector.

Fig. 16 is a second-third selector with two normal levels.

Fig. 17 is a second selector for releasing first selector over special conductor.

Fig. 17A is a detail of lower contact closing springs engaged by shaft cam. The upper set of contact closing springs is similar.

Fig. 18 is a second selector adapted to select one of two thousands with one normal level.

Fig. 19 is a well known type of connector.

Fig. 20 is a 200-point bank connector.

Fig. 21 is a repeater.

Fig. 21A shows wiring between repeater Fig. 21 and selector banks.

Fig. 22 is a first-third selector for sub-office.

Fig. 22A is a detail of cam spring contact and cam Z22. 60

Fig. 22B is a plan view of normal level shown in Fig. 22.

Fig. 23 is a first selector.

Fig. 24 is a rotary repeater.

Fig. 25 is a system plan. 65

Fig. 26 is a first selector with meter.

Figs. 27 to 41 inclusive are diagrammatic "keys" to descriptions of involved figures hereinafter referred to in the specifications and indicated in the respective "keys". 70

The present invention comprehends a six-digit or "1,000,000" line capacity automatic telephone exchange system in which subscribers' lines are grouped into branch offices of ten-thousand lines each, or are tributary to such a branch office through a sub-office or so-called satellite office of the branch office. All ten-thousand groups of a hundred-thousand group are made tributary to a group center. The group centers are then inter-connected by trunks. Thus, a call will route from its ten-thousand group to its hundred-thousand switching center, and thence through a second hundred-thousand switching center, and to its called ten-thousand group, or if the call is to a line of the calling group, to be diverted back to the group containing the calling line; the Fig. 25 showing the general trunking arrangement. 75

In Fig. 25, the large squares indicate the hundred-thousand groups. The small squares in the large squares indicate the switching center for the particular hundred-thousand group. The numbered circles within the large squares represent the indexed ten ten-thousand groups or offices. The quadri-lateral enclosures indicate the groups or group and the center enclosed are contiguous; perhaps located under the same roof. The larger circle outside the large square in the upper left-hand corner of the sheet represents a sub-office or satellite subordinate to the "9" ten-thousand group of the "2" hundred-thousand group, and contains the "3" and "4" thousands of the said "9" ten-thousands group or office. 80

In Figs. 27 to 41, the circles each denote an equipment element detailed in the designated drawing figure. The circles within squares denote the equipment elements denoted by the figures therein are in the same office, while the lines running between the squares denote an inter-office trunk. The lines extending from a circle 105

110

outside a square to a circle within a square, respectively, denote subscriber lines.

In carrying out the plan of the system of the present invention a number of switch mechanisms are employed, looking to combining into single switch units means of performing alternative switching operations heretofore requiring a plurality of specific switch units, so far as I am aware. That is, for example, where a first selector is located in a double office (as circles "2" and "3" in the "4" square of Fig. 25), the first selector will not only have access to groups of trunks leading to the "4" switching center, but will also have access to specific groups of local trunks leading within the said "2" and "3" offices. Under this condition, if "4" is the first digit pulled, it may mean any of the ten offices of the "4" hundred-thousand group may be under call. However, the second digit pulled will determine to what ten-thousand group or office of the said "4" group the call is destined. The Fig. 37 may be referred to in this connection, wherein the selector Fig. 11 selects a trunk to a selector Fig. 26, located in the "4" switching center, the repeater Fig. 24 being interposed in the trunk. The second digit pulled will progress the call through operating the said selector Fig. 26. However, the selector Fig. 11 will be caused to restore from the trunk to Fig. 26 through the agency of repeater Fig. 24 and incidentally switch the switch connections to the wipers of said selector Fig. 11 responsive to digit "2" or digit "3" only, so the third digit pulled will cause the selector Fig. 11 to again operate and extend the call over one of the group of trunks to the "2" or the "3" office of the "4" hundred-thousand group, to which the calling line belongs, as the case may be; determined by the second digit, if "2" or "3", through the agency of Fig. 24. The thousands group of trunks will be determined by the third digit and will refer to the ten-thousand group of the "4" hundred-thousand group indexed by the second digit. The last three digits will serve to complete the call.

Another organization is represented by Fig. 39 wherein the call is from a line tributary to a sub-office containing the "3" and "4" thousands of the "9" ten-thousand group of the "2" hundred-thousand group. Upon the initiation of the call, the calling line is automatically extended to first selector Fig. 26 in the "2" switching center and also to the switch Fig. 22 in the satellite. The first digit sent will then be effective to said selector Fig. 26 to progress the call ahead to the successive selector Fig. 26. It will also coincidentally be effective to operate the switch Fig. 22 as an eliminating switch on its normal level. The second and the third digits sent will be effective to progress the call ahead to the second and third successive selectors Fig. 26. It will also be coincidentally effective to operate the switch Fig. 22 as before. However, the third digit sent will determine if the extension of the call will be destroyed preparatory to the switch Fig. 22 operating now as a fourth selector to progress the call to the connector Fig. 19 in the satellite office towards the called line if in the same sub-office or satellite, or it will alternatively disable the switch Fig. 22. That is, depending upon the destination of the call (if to a line of the same sub-office as contains the calling line, or to a line tributary to some other office) as indexed by the first three digits sent, will cause the switch Fig. 22 to become prepared to function to extend the call as a selector of the fourth numerical order,

or alternatively become disabled whereby the call will be normally progressed from the third selector Fig. 26.

Another organization is represented by Fig. 32 wherein the first selector Fig. 26 located in the "5" ten-thousand office of the "4" hundred-thousand group, is automatically attained consequent to initiating the call. The selector Fig. 26 will operate responsive to the first digit to extend the call through a repeater Fig. 21 over a trunk to the "4" switching center, there terminating in selector Fig. 26. The second selector Fig. 26 will be responsive to the second digit to extend the call through a repeater Fig. 21 and over its trunk to the "6" or the "7" office as the case may be, in correspondence with the second digit, terminating the call in Fig. 18. However, the level at which the second repeater Fig. 21 of the trunk is seized by second selector Fig. 26 will determine the specific functioning of the second repeater Fig. 21 and also the selector Fig. 18. For example, if the second repeater Fig. 21 is seized from one level, a temporary ground will be applied over the minus trunk outgoing from the repeater to cause the selector Fig. 18 at the far end of the trunk to shift the switch connections from the normally connected wipers to an alternative set of wipers, so the next (third) digit sent will operate the selector Fig. 18 in a normal manner, but with operative reference to the group of trunks cooperative with the alternative wiper set. Had the second repeater been seized from another level, the preliminary shifting of wipers would not take place, so the normally accessible group of trunks would be operatively concerned upon the next (third) digit being sent. That is, the digit sent to operate the switch (second selector Fig. 26) seizing the two-wire trunk leading to selector Fig. 18 will determine what group of trunks may be thereafter selected by the selector Fig. 18 terminating the trunk. Thus, when two ten-thousand groups are installed contiguous (as the "6" and "7" ten-thousand groups in the "4" hundred-thousand group), a single group of trunks; each trunk thereof leading to selector as Fig. 18, will be accessible to trunks leading from the banks of its terminating selector Fig. 18 to each of the latter said ten-thousand groups.

Another organization is represented by Fig. 34 wherein selector Fig. 9 terminates a trunk accessible from three levels of selector Fig. 26, and in which trunk repeater Fig. 21 is interposed. The selector Fig. 9 will automatically function on its normal level responsive to being seized by the antecedent selector, to thereby extend or tandem the call to one of two groups of trunks, depending upon from what of two of the levels the trunk is seized. Upon seizing the said trunk from another level the selector Fig. 9 will remain inert, preparatory to being directly operated from the calling line. The directive operation will determine how the selector Fig. 9 will operate, as if a predetermined digit is sent, it will restore its shaft to normal and shift the wiper connections so the succeeding digit sent will obtain access to a higher numerical order set of trunks than would have been accessible had not the digit been a predetermined one. Thus, sending the predetermined digit causes the numerical order corresponding to the said digit to be negated, so that one less linking switches will be required in extending a call comprised of a plurality of digits, than the number of digits, due to the elimination of a numerical order switch group.

To simplify descriptions well known elements

shown in the drawings are designated as follows:

5 "O. N." designating off-normal contacts operated by either vertical or rotary movement of shaft; "R. O. N." designating off-normal contacts operated by rotary movement of shaft only; "V. M." designating vertical magnet; "R. M." designating rotary magnet; "C. S." designating cam springs operated upon the 11th rotary position of shaft being attained; "RLSE. M." designating release magnet. "RLSE.SIG." designating release signal wire; "RLSE.TRK." designating release trunk; "BUSY & GRD." designating ground wire to cam spring carrying busy tone; 10 "SUPY.SIG." designating battery supply through supervisory relay; "INT.START." designating conductor leading to ringing control relay; "+TRUNK" designating plus outgoing trunk; "-TRUNK" designating minus outgoing 15 trunk; "-LINE" designating minus line wire; "+LINE" designating plus line wire. SUPY.-GRD. means that this conductor extends to ground through a supervisory relay.

In the following, for brevity in describing the 20 various elements, selectors will be described as "stepping up" when in fact what is meant is the shaft of the selector is moved vertically by successive steps. Also the selector will be described as "rotating to a non-busy trunk" when in fact what is meant is that the shaft is given a rotary movement causing wipers carried by said shaft to engage successive sets of trunk and co-ordinate contacts until an idle set is reached and seized.

25 In the following descriptions, the detailed circuits will not be repeated for the various switches wherein such switches are well known or contain structures as elements thereof which correspond to elements of well known switches shown, or 30 of other switches of the present invention described, as their operation with relation to the said elements will be understood. By way of illustrating the application of my invention I shall set forth herein a system embodying same, 35 together with description of typical call routings.

Referring to Figs. 25 and 27, making a call from telephone 423456 to telephone number 434567. The call will route from telephone set 40 Fig. 2, to lineswitch Fig. 3, to first-third selector Fig. 11, to second-third selector Fig. 17, back to first-third selector Fig. 11, to fourth selector Fig. 12, to connector Fig. 19, thence to called telephone Fig. 2.

45 Upon calling party removing receiver from hookswitch circuit will be closed over line wires to lineswitch, plumping same in the well known manner, the calling line being thereby extended to first-third selector Fig. 11. Upon calling party pulling digit "4" on sending device said first-third sector Fig. 11, will respond by stepping up to the 4th level and there rotate to a non-busy trunk, the calling line being thereby extended to said second-third selector Fig. 17. Upon pulling 50 second digit "3" on sending device said second-third selector will step up to the 3rd level and there rotate to the first set of contacts, and at the same time close contact X17 by means of cam Z17, thereby extending ground through said latter contacts back over bank contacts of said first-third selector Fig. 11, to wiper a11 through contacts on relay N11, thence to winding of relay F11, thereby closing contacts of the latter relay and locking its armature through its winding 55 by means of ground which is obtained through

contacts on relay B11. This ground is also extended through contacts on relay N11, contacts on relay L11, contacts on relay H11, thence to winding of release magnet to battery, thereby actuating the said release magnet to restore the shaft to normal. The said ground through contacts of relay F11 is also extended through contacts of relay H11 upon relay H11 deactuating due to off-normal springs opening consequent to the restoration of the shaft, to winding of relay N11, thereby causing said relay N11 to actuate, which in turn disengages wipers c11 and d11 from the circuits and connects instead wipers e11 and f11 respectively. Relay N11 will be locked through its upper armature and lower armature of relay F11 to the release trunk.

At the time the shaft of Fig. 11 is restored relay D11 will be actuated when the wipers are freed from the bank contacts because relay D11 is then not short-circuited and current is therefore derived through it to the release trunk from the winding of relay E11 by way of the contacts on relay H11. This will endure until relay H11 deactuates upon the shaft restoring, whereupon the said energizing circuit of relay D11 will be opened. When relay D11 actuates, relay A11 will deactuate and deenergize relay B11, but relay B11 has a slow release characteristic which causes it to sustain until the shaft restores and relay A11 is re-associated and actuates to re-energize relay B11 before the deactuation of relay B11 occurs, so no laps of ground potential occurs to the contacts engaged by the upper armature of relay B11.

55 In other switches of the system of the present invention relays having a corresponding function and characteristic to relay B11 are employed; Figs. 7, 8, and 9, for example.

When shaft is stepped off-normal relay H11 is actuated, closing and opening its contacts. 60 Upon the release to normal of shaft of first-third selector Fig. 11, as above described, second-third selector Fig. 17 will restore to its free, normal condition. Relays F11 and N11 are locked actuated at this juncture. First-third selector Fig. 11 is now in a position to receive the third digit "4", which upon being pulled on sending device steps the shaft up to the 4th level and there rotates to a non-busy trunk, the calling line being thereby extended to wipers e11 and f11 and 65 to their companion bank contacts, thence to a 20-point bank selector Fig. 12. Upon pulling fourth digit "5" on sending device, shaft of selector Fig. 12 is stepped up to the 5th level and there rotates to a non-busy trunk the calling line being thereby extended to connector switch Fig. 19. Selector Fig. 12 is so arranged that it will select one of twenty bank contacts located ten in a row in two rows or levels. In the said selector having twenty bank contacts the wipers will rotate over the space of but ten contacts. Relays D12 and F12 are used for the purpose of stopping shaft when the switch wipers are on the first non-busy contact when rotating. If wiper c12 finds a ground on any bank contact said ground 70 will be carried through wiper to contacts on relay F12, to contacts on relay D12, thereby shunting relay D12 from the circuit to relay E12, through contacts on rotary magnet to contacts on off-normal springs, thence to winding on relay E12. Wiper c12 upon finding ground will extend the same through contacts on relay D12, thence to resistance G12 and winding of relay F12, thereby shunting the latter from the circuit. 75 If wiper a12 should not obtain ground relay D12

will operate in the well known manner. If wiper c12 should not obtain ground through bank contacts relay F12 will be actuated by reason of obtaining ground through contacts of relay B12, through rotary off-normal contacts, to winding of relay F12, to resistance G12, thence to free pole of battery. Upon relay F12 becoming actuated the trunk will be switch from private wiper a12 to private wiper c12 and line wiper pair b12, to line wiper pair d12. Rotary off-normal contacts are closed upon first rotary movement of the shaft and remain in that condition until the shaft is returned to its normal position. Upon said wipers seizing a non-busy trunk, the calling line is thereby extended to connector Fig. 19, the operation of which is well known; the said connector having access to bank contacts "67" and there completes the call to the called telephone Fig. 2.

Referring to Figs. 25 and 28, making a call from telephone number 623456 to telephone number 634567. The call will route from the subscriber's telephone set Fig. 2, to lineswitch Fig. 3, to first selector Fig. 26, to second-third selector Fig. 16, to fourth selector Fig. 26, to connector Fig. 19, thence to called telephone Fig. 2.

Upon calling party removing receiver from hook-switch, circuit will be closed over line wires to lineswitch, plunging same in in well known manner, the calling line being thereby extended to first selector Fig. 26, in the well known manner. Upon calling party pulling first digit "6" on sending device said first selector will respond in the well known manner, stepping up to the 6th level and there rotate to a nonbusy trunk, the calling line being thereby extended to second-third selector Fig. 16. Upon pulling second digit "3" on sending device the said second-third selector will step up to the 3rd level and there rotate to the first contact after which the shaft will release to normal and at the same time switch from private wiper a16 to private wiper c16 and from line wiper pair b16, to line wiper pair d16, through the agency of relay N16.

The release to normal of the shaft in said second-third selector Fig. 16 is accomplished as follows: Upon wiper a16 engaging the first bank contact in the third level current is projected over said wiper a16 from winding of relay E16, through contacts on relay H16, contacts on rotary magnet, contacts on relay D16, contacts on relay N16, contacts on relay L16, thence to private wiper a16, over private bank through contact on relay N16, lower winding of relay F16, thereby closing contacts of said relay F16 which receive ground from contacts on relay B16, extending said ground through contacts on relay N16, contacts on relay L16, contacts on relay H16, thence to winding of release magnet and to battery on release signal wire, thereby actuating said release magnet which in turn restores shaft to normal, at the same time opening off-normal contacts, which in turn open ground to off-normal relay H16, allowing it to restore to normal, thereby extending said ground on relay F16 through contact on relay H16 to winding on relay N16, actuating said latter relay for the purpose of switching from wiper a16 to private wiper c16 and from line wiper pairs b16 to line wiper pairs d16. Relay N16 upon actuating closes contacts theron which cause it to remain actuated locked to the release trunk. Second-third selector Fig. 16 is now in condition to receive the third digit "4", which upon being pulled on sending device steps the shaft to the 4th level at which point it

rotates and cuts in in the usual manner, stopping on a non-busy set of contacts the calling line being thereby extended to selector Fig. 26. The fourth digit "5" is now pulled on sending device, which raises shaft of selector Fig. 26 to the 5th level and further operates in the well known manner, the calling line being thereby extended to connector Fig. 19, the operation of which is also well known; the said connector having access to the bank contacts "67" and there completes the call to the called telephone Fig. 2.

Referring to Figs. 25 and 29, making a call from telephone number 843216 to "wirechief's" switchboard located contiguous to the "4" ten-thousand group of the "8" switching center. The call will route from telephone set Fig. 2 to line-switch Fig. 3, to first selector Fig. 7; thence to receiving circuit Fig. 5.

Upon calling party removing receiver from hook-switch on telephone the circuit will be closed over line wires, to lineswitch, plunging the same in, the calling line being thereby extended to selector Fig. 7. Upon calling party depressing push key A2 located at telephone, resistance R2 will be included in the line to selector Fig. 7. 100 Tracing the circuit through the various relays it will be noted that current flows through the upper winding of relay A7, upper winding of relay F7, to winding of relay G7, through contacts on relay D7, over minus side of line through 105 telephone Fig. 2, back to Fig. 7 by way of the plus side of the line, through contacts on relay D7, through lower winding of relay F7, through lower winding of relay A7, through cam springs, thence to ground. 110

It will be noted that current flowing through the several relays will cause relay A7 to be actuated; relay F7 being differentially wound will not become actuated. Relay G7, due to mechanical adjustment and low resistance, will not be actuated during the time that resistance R2 is included in the circuit. From the fact that relay G7 is not actuated, ground will be extended from contacts of relay A7 contacts on relay G7, contacts on relay H7, thence to winding of relay E7. Said relay E7 becomes actuated, closing circuit to rotary magnet which causes shaft to rotate its wipers to a non-busy trunk, the calling line being thereby extended to receiving circuit Fig. 5. 115 120

Had "information" switch-board (located con- 125
tiguous to the "4" ten-thousands group of the
"8" switching center) been desired in lieu of
"wirechief's" switch-board the calling subscriber
would have depressed push key B2 in place of
push-key A2, thereby grounding the minus side 130
of the line to Fig. 7, causing relay F7 to become
unbalanced, in which condition it is caused to
be actuated. Ground being extended from con-
tacts on relay A7 to contact on relay F7 (also
contact on relay G7), it will now be extended to 135
the winding of relay N7 to actuate it and also
through contact on relay H7 to the winding of re-
lay E7, causing the latter to become actuated for
the purpose of closing a circuit to the rotary 140
magnet which operates the shaft rotarially to a
non-busy trunk, the calling line being thereby
extended to receiving circuit Fig. 5. Upon the
operation of relay F7 ground is extended from 145
its contacts to the winding of relay N7, which
causes said latter relay to become actuated for
the purpose of shifting private wiper a7 to pri-
vate wiper b7 and line wipers c7 to line wipers d7.
Relay N7 locks first to the release trunk through
the upper armature of relay B7, and when the 150
relay D7 actuates to effect seizure, whereupon

relay A7 will deactivate, the locking of said relay N7 will be sustained through the lower armature of relay D7 to the upper armature of relay A7 before the upper armature of relay B7 retracts.

Referring to Figs. 25 and 30, making a call from telephone number 532981 to telephone number 532672. The call will route from subscriber's telephone set Fig. 2, to the line-switch Fig. 3, to first selector Fig. 26, to second-third selector Fig. 14, to fourth selector Fig. 26, to connector Fig. 19, thence to called telephone Fig. 2.

Upon calling party removing receiver from hook-switch on telephone the circuit will be closed over line wires to lineswitch, plunging same in, the calling line being thereby extended to first selector Fig. 26, in the well known manner. Upon calling party pulling first digit "5" on sending device said first selector will respond by stepping up to the 5th level and there rotate to a non-busy trunk, the calling line being thereby extended to second-third selector Fig. 14.

Upon calling the second digit "3" on sending device the shaft in Fig. 14 will respond by stepping up to the 3rd level and there rotate the first contact where release wiper a14 receives ground from the bank contact. This ground applied through contact of relay N14 will operatively energize relay G14 wherein it will lock to the release trunk and apply ground through off-normal springs to the release magnet, causing said shaft to release to its normal position. Relay D14 will actuate, energized from the winding of relay E14 incidental to the restoration of the shaft, but due to the slow-release characteristic of relay B14 it will sustain until relay D14 deactuates upon the shaft restoring, whereat the off-normal spring set will operate to open the energizing circuit for relay D14.

Upon shaft returning to its normal position and closing off-normal springs it will be noted that ground through contacts on relay G14 will be now extended through off-normal contacts, thence to the winding of relay N14, causing the latter relay to become actuated for the purpose of shifting the incoming release trunk and lines from private wiper b14, to private wiper c14 and from line wipers e14 to line wipers d14. Second-third selector Fig. 14 is now in a condition to receive the third digit "2", which upon being pulled on sending device steps the shaft up to the 2nd level and there rotates to a non-busy trunk, the calling line being thereby extended to fourth selector Fig. 26. Fourth digit "6" being now pulled on sending device said fourth selector Fig. 26 will respond by stepping up to the 6th level and there rotate to a non-busy trunk, the calling line being extended thereby to connector Fig. 19, the operation of which is well known, the said connector having access to bank contacts "72" and there completes the call to the called telephone Fig. 2.

Referring to Figs. 25 and 31, making a call from telephone 213456 to "long distance" switchboard located contiguous to "8" switching center. The call will route from the subscriber's telephone set Fig. 2, to lineswitch Fig. 3, to first selector Fig. 26, to repeater circuit Fig. 21, to lineswitch Fig. 3, to holding circuit Fig. 1, to selector Fig. 7, thence to receiving circuit Fig. 5.

Upon calling party removing the receiver from hookswitch on telephone, circuit will be closed over line wires to lineswitch, plunging same in, the calling line being thereby extended to first selector Fig. 26, in the well known manner. Upon

calling party pulling "0" on sending device said selector will respond in well known manner, stepping up to the "0" level and there rotate to a non-busy trunk extending to repeater shown in Fig. 21. The said repeater Fig. 21 is connected to trunk to switching center "2", thence to line-switch Fig. 3, thence to holding circuit Fig. 1. The latter circuit is associated with the outgoing end of the trunk to switching center "3" at which point selector Fig. 7 terminates said trunk.

The action of the holding circuit relays of Fig. 1 is as follows:

When lineswitch Fig. 3 plunges in, extending calling line through holding circuit Fig. 1 to selector Fig. 7 relay A1 being in series in the minus side of the line, is thereby energized, closing ground through its contacts to relay B1, which in turn closes ground through its contacts back over the release trunk to the lineswitch Fig. 3, thereby holding the said lineswitch plunged into outgoing trunk.

Fig. 21 is a repeater of the well known type with the addition of relays G21, H21 and N21 for the purpose of introducing certain conditions in the trunk with which it is associated. The said relays G21, H21 and N21 are operated through the several release trunks shown in Fig. 21, which extend back to the banks of the selector Fig. 26. The details of connection between Fig. 21 and bank contacts of said switch Fig. 26, are shown in Fig. 21A. Referring to the latter figure, a21, b21 and c21 represent release trunk terminals of levels "0", "9" and "8" respectively, while a'21, b'21 and c'21 represent line trunk terminal pairs of levels "0", "9" and "8" respectively. It will be noted that the said line trunks are in multiple relation, while the said release trunks are likewise in multiple relation after the operation of relay G21.

Normally the release trunks leading from a21 and b21 are connected to windings of relays H21 and N21 respectively, thereby placing said relays in the position to receive battery over said trunks leading from a21 and b21. If relay H21 be actuated by means of battery from said trunk leading from a21 its contacts will close ground through to winding of relay G21, thereby actuating same, for the purpose of locking itself and connecting said trunks leading from a21 and b21 to the trunk leading from c21 and also to open the circuit of relay H21. The action of relay N21 would be the same as relay H21 if it received battery over said trunk leading from b21 from private bank wiper of selector Fig. 26. Thus wipers reaching any of the said contacts will obtain access to the same lines and release trunk through Fig. 21.

Incidental to the action of relay N21 resistance R21 is introduced into the minus side of the line.

Incidental to the action of relay H21 a ground is introduced on the minus side of the line. Relays H21 and N21 are slow in releasing while relay G21 is slow in closing. Thus there is an appreciable time during which the said introduction of resistance and the said grounding of the minus side is respectively maintained.

Connection to a release trunk contact in level "8" will obtain access to said repeater in the well known manner. Thus trunk branches reaching from banks in levels "8", "9" or "0" all finally terminate in said selector Fig. 7.

The functioning of relays G21, H21 and N21 will be understood in view of the fact that upon relay D26 of the seizing selector Fig. 26 actuating, followed by the upper armature of its relay B26

retracting, battery through the windings of relays E26 and D26 in series of the seizing selector is applied over the private wiper directly to the release trunk of the repeater Fig. 21 or through the upper winding of relay H21 or relay N21 to the latter said release trunk, depending upon which of levels "8", "0" or "9" is seized, respectively. This is having in mind that upon relay D26 actuating, the relays A21 and B21 will actuate to locally apply ground to the release trunk of the repeater Fig. 21. The lower armature on relay G21 is adjusted to engage its make spring before disengaging the armature resting contact, though due to the core slug, it would continue to attract should the said resting contact disengage whereby the relay winding would thereby become de-energized.

It will be noted that if the repeater Fig. 21 is seized from the "8" level (c21) of selector Fig. 26, the release trunk branches of the "0" and "9" levels includes the upper windings of relays H21 and N21, respectively. The resistance value of the latter said windings are each low enough to insure guarding the repeater Fig. 21 if tested through a branch leading to a21 or b21 and at the same time will not operate the relays H21 or N21, as the case may be, to disturb the outgoing minus trunk if so tested, because of being slightly sluggish in actuating due to the slugs thereon for causing them to be slow-releasing. A testing selector will thus rotate-off a tested contact applied to ground including a said winding of relay H21 or N21 before a latter said relay will operatively energize.

From the fact the said wiper of first selector Fig. 26 engages a contact on the "0" level in the stated call, repeater Fig. 21 will apply ground over the minus side of incoming trunk to selector Fig. 7. The minus side of the said trunk entering selector Fig. 7 passes through contacts of relay D7 through winding of relay G7, thence through upper winding of relay A7 to free pole of battery. The plus side of the said trunk entering said selector Fig. 7 passes through contacts of relay D7, lower winding of relay F7, lowering winding of relay A7, thence through contacts of cam springs to ground. Windings of relay F7 are so connected that when current is flowing through both the electromagnetic action of each winding will oppose the other. Relay F7 being unbalanced from the fact the minus side of the line is grounded for an appreciable time, will actuate. Relays A7 and G7 being in circuit will remain actuated so long as current flows over trunk. The closing of contacts on relay F7, contacts of relay A7 being closed, causes relay E7 to actuate, thereby closing a circuit to the rotary magnet which in turn will cause said rotary magnet to actuate in the well known manner. A second contact on relay F7 closes a circuit through winding of relay N7, causing it to actuate and lock to ground at relay E7. The actuation of relay N7 will close line wipers d7 and private wiper b7 to contacts on relay D7 in lieu of line wipers e7 and private wiper a7. The shaft of said Fig. 7 will be caused to rotate to a non-busy set of bank contacts by the well known action of the rotary magnet and associated relays. Incidental to the off-normal movement of the said shaft relay H7 will actuate from the closing of the off-normal springs; the contacts of said springs being designed to close on any off-normal movement. The operation of relay H7 shunts relays F7 and G7 from the circuit leaving relay A7 only in circuit. When wipers seize a

non-busy contact set extending to equipment Fig. 5 on the "long distance" switch-board relay D7 operates in the well known manner, extending the plus and minus lines to the wipers d7 and also extends release trunk to wiper b7, thence to receiving circuit Fig. 5. Thus relay A5 is actuated by reason of current flow in circuit back through repeater. Resultant to the actuation of relay D7, relays A7 and B7 will deactivate in sequence, the locking circuit for relay N7 being closed through lower armature of relay D7, upper armature of relay A7 to ground before upper armature of relay B7 retracts, so relay N7 will be sustained locked.

From the fact relay A5 is actuated ground is closed through its contacts to wiper b7, thence through contacts on relay N7, upper armature of relay D7 to the release trunk of Fig. 7 to maintain ground thereon, relay D7 being thus maintained energized. Incidental to actuation of relay A5 signal S5 on the switchboard will display. "Long distance" operator will respond by manipulation of key.

If calling party should have pulled "9" in lieu of "0" the action to repeater Fig. 21 would be the same as before with the exception, as outlined, that relay N21 would operate thereby introducing resistance R21 in the minus side of the trunk to selector Fig. 7. The operation of Fig. 7 will be the same as before described with the exception that due to the introduction of resistance R21 in the minus side of trunk, relay G7 will not receive enough current to cause it to actuate and relay F7 will not become unbalanced and sustain actuated. Therefore, the contacts of relay G7 become closed, which completes the rotary magnet circuit into operative condition as before described. The shaft will be rotated, and wipers b7 and d7 being disassociated by virtue of relay N7 being unenergized, wipers a7 and c7 will seize a non-busy trunk to manual operator's equipment Fig. 5 and will operate as before described in relation to "long distance", the manual operator responding to and if desired extending the call.

If calling party should have pulled "8" on sending device in lieu of "0" or "9", desiring to call 843216, for instance, the action to repeater Fig. 21 would be the same as before with the exception that relays G21, H21 and N21 would not become operatively included into the circuits the pulling of "8" on sending device would extend the telephone Fig. 2 to the minus and plus lines of selector Fig. 7, reaching the windings of relays A7, F7 and G7 included serially, thereby actuating said relays A7 and G7, but not F7, due to the latter relay being differentially wound. If second digit "4" is next pulled on sending device, relay A7 will be responsive to transmit the proper number of impulses to the vertical magnet, thereby stepping the switch up to the fourth level where it will rotate-in and seize the first non-busy trunk leading to a selector. Incident to the first open impulse effective in relay A7 relay H7 will be operated through the off-normal contacts, thereby excluding the windings of relays F7 and G7 from the path including the windings of relay A7. The operative electrical circuits in off-normal positions are therefore the same as in the well known type referred to and shown in Fig. 26. The switches involved in the remainder of the call are of the said well known type.

Referring to Figs. 25 and 32, making a call from telephone number 451234 to telephone number 464567. The call will route from telephone set Fig. 2, to lineswitch Fig. 3, to first selector Fig. 26,

to repeater circuit Fig. 21, to second selector Fig. 26, to repeater Fig. 21, to selector Fig. 18, to selector Fig. 26, to connector Fig. 19, thence to called telephone Fig. 2.

- 5 Upon calling party removing receiver from hook switch on telephone circuit will be closed over line wires to lineswitch, plunging same in, the calling line being thereby extended to first selector Fig. 26 in the well known manner. Upon 10 calling party pulling first digit "4" on sending device said selector will respond in the well known manner, stepping up to the 4th level and there rotate to a non-busy trunk, the calling line being extended to repeater Fig. 21. The said repeater 15 is connected in said trunk between the 4th level and the trunk wires leading to switching center "4"; thence to second selector Fig. 26 therein. The operation of Fig. 21 has been described.

Upon calling party pulling second digit "6" on

- 20 sending device said second selector will respond by stepping up to the 6th level and there rotate to a non-busy trunk in the well known manner, the calling line being thereby extended to repeater Fig. 21. 25 The private wire from the 6th level (assuming e^{21} to represent the 6th level) of second selector Fig. 26, described, is extended as release trunk No. 2 to repeater Fig. 21 reaching upper winding of relay H21, thereby actuating the latter relay 30 to close ground through its contacts to the minus side of the line, same figure; the minus and plus lines of repeater Fig. 21 being extended over trunk to selector Fig. 18 current will flow through upper winding of relay A18, upper winding of relay F18, 35 through winding of relay G18, through contacts of relay D18, thence to minus side of line, contacts of relay A21, plus side of line, contacts of relay D18, lower winding of relay F18, lower winding of relay A18 to ground on cam springs. It 40 will be noted that ground from repeater Fig. 21 over minus side of line will unbalance differentially wound relay F18, causing same to be actuated, extending ground from contacts on relay A18 to winding of relay N18, thereby actuating 45 and locking the latter relay through upper armature of relay B15 for the purpose of switching release trunk from private wiper a18 to private wiper b18 and the line conductors from line 50 wipers c18 to line wipers d18. It will be noted that relays A18, F18 and G18 are in a position to be actuated through the loop circuit through repeater Fig. 21, the ground on the minus side of the loop applied by relay H21 causing the windings of relay F18 to be unbalanced, and therefore 55 relay F18 will actuate.

Upon shaft of selector Fig. 18 becoming in an off-normal position (due to the third digit "4" being sent) off-normal contacts will be closed, extending ground to winding of relay H18, thereby 60 causing it to actuate for the purpose of excluding the windings of relays F18 and G18 from the circuit just described. Selector Fig. 18 is now in a condition to receive the third digit "4", which upon being pulled on sending device steps up to the 4th level and there rotates to a non-busy trunk, the calling line being thereby extended over private wiper b18 and line wipers d18, through bank contacts of selector Fig. 18 to fourth selector Fig. 26.

70 Upon calling party pulling the fourth digit "5" on sending device the selector Fig. 26 will be stepped up to the 5th level and there rotate to a non-busy trunk in the well known manner, the calling line being thereby extended to connector Figure 19 the operation of which is well known,

the said connector having access to bank contacts "67" and there completes the call to the called telephone Fig. 2.

Had the last call been to 473456, upon pulling the second digit "7" on sending device in place of "6", the release trunk from selector Fig. 26 would have been extended to repeater Fig. 21 over the regular release trunk (assuming c21 to represent the seventh level), thereby causing said repeater to operate in the well known manner without introducing a ground impulse on minus line or a resistance in the minus line. Referring to selector Fig. 18, relay F18 not having received ground from minus side of line would remain in normal position, as well as relay N18, which retains private wiper a18 and line wipers c18 in a condition to extend calling party to selector Fig. 26 over middle set of line banks and upper contacts of private banks; the selector Fig. 26 as applied in this case reaching a different thousand group than when the second digit sent was "6".

In this connection, in view of previous descriptions, if the second digit of a called number is one that corresponds to the release trunk No. 3 (b21), relay N21 will cause resistance R21 to be momentarily introduced into the trunk circuit leading to selector Fig. 18 wherein the relay G18 is serially included. The relay G18 actuated under the before described seizures for no operative purpose, but under the condition of resistance R21 being included it retracts while relay H18 is normal to allow a circuit path to be closed from the winding of relay E18, armature of relay H18, armature of relay F18 to the ground on lower armature of relay A18. This will cause relay E18 to actuate 100 while relay H18 is normal to energize the rotary magnet and close the off-normal springs to operate relay H18 for the objects explained, the shaft rotating selectively on its normal level to hunt and seize the first idle trunk in the manner of operating at an off-normal level. Manifestly, in view of other descriptions herein as well as the characterization of Fig. 18 at the outset the trunks of the normal level may extend to a selector Fig. 26 (not shown) for further extension responsive 105 to the next digit sent. Under this condition the selector Fig. 18 upon being seized through the No. 3 release trunk bank set will automatically tandem a trunk connection before the next digit of the called number is sent by the calling party. 110 That is, if the second digit is a predetermined one, two specific trunk group links will be inter-linked in tandem responsive thereto.

Referring to Figs. 25 and 33, making a call from telephone number 78123 to telephone number 78324. The call will route from telephone set Fig. 2 to the line switch Fig. 3, to first-second selector Fig. 8, to selector Fig. 26, to connector Fig. 19, thence to called telephone Fig. 2.

Upon calling party removing receiver from 115 hookswitch on telephone the circuit will be closed over line wires to lineswitch, plunging same in, thus extending line from calling party's telephone to first-second selector Fig. 8 in the well known manner.

Upon calling party pulling first "7" on sending device selector Fig. 8 will respond by stepping up to the 7th level and there rotate to first contact set where private wiper a8 engages bank contact, thereby extending circuit from winding 115 of relay E8, contacts on relay H8, contacts on rotary magnet, contacts on relay D8, contacts on relay N8 to private wiper a8, bank contact, contact on relay N8, thence to lower winding of relay G8, causing the latter relay to be actuated 120

for the purpose of locking its armatures closed through its upper winding by means of ground extended from contacts on relay B8. The closing of contacts of relay G8 also extends ground 5 through contacts on relay N8, contacts on relay H8 to release magnet, actuating same for the purpose of restoring shaft to normal. Upon shaft restoring to normal, offnormal contacts are opened, thereby causing relay H8 to restore to 10 normal. Upon relay H8 being restored to normal, ground is extended through contacts on relay G8, contacts on relay H8, to winding of relay N8, causing the latter relay to actuate, thereby switching private conductor from wiper a8 to 15 wiper b8 and incoming line from wipers c8 to wipers d8. The off-normal contacts E. O. N. operate if the shaft rotates from normal position or steps vertically. At the time wiper a8 retracts from the bank contact grounded through the 20 lower winding of relay G8, and while the shaft is restoring to normal the relay D8 will be operatively energized from the winding of relay E8 through contacts on relay H8, through the winding of said D8 to the release trunk grounded 25 through the upper armature of relay B8. Upon subscriber now pulling second digit "8" on sending device the shaft of first-second selector Fig. 8 will respond by stepping up to the 8th level and there rotate to a non-busy trunk, the calling 30 line being thereby extended to selector Fig. 26. On pulling third digit "3" on sending device selector Fig. 26 operates in the well known manner, obtaining access to connector Fig. 19, the operation of which is also well known, the said connector having access to bank contacts "24" and there completes the call to the called telephone 35 Fig. 2.

Selector Fig. 8 thus has access to trunks through wipers a8 and c8 and to a different set of trunks 40 through wipers b8 and d8. Since a digit is negated when the wipers a8 and c8 are effective, the trunks engaged by them will correspond to a numerical order one higher than those reached by wipers a8 and d8.

45 Referring to Figures 25 and 34, making a call from telephone number 451234 to "long distance" switchboard located contiguous to "8" switching center. The call will route from telephone set Fig. 2 to the lineswitch Fig. 3, to the first selector Fig. 26, to repeater circuit Fig. 21, to second-third selector Fig. 9, thence to receiving circuit Fig. 5.

Upon calling party removing receiver from hookswitch on telephone circuit will be closed over line wires to lineswitch, plunging same in, 55 the calling line being thereby extended to first selector Fig. 26 in the well known manner. Upon calling party pulling "0" on sending device said selector will respond in the well known manner, stepping up to the "0" level and there rotate to 60 a non-busy trunk contact, extending call to repeater Fig. 21.

The said repeater Fig. 21 is interposed in a 65 trunk to switching center "8" leading to second-third selector Fig. 9. It has been stated Fig. 21 is the well known type of repeater with the addition of relays G21, H21 and N21, the said relays being for the purpose of introducing certain conditions into the trunk extending from same, the operation of which has been described 70 (213456 to "long distance" switchboard). Referring to said description, while assuming the bank sets a21, b21 and c21 refer to the "0", "9" and "8" levels, respectively, as before. From the fact the said wiper of first selector Fig. 26 engages a 75 contact on the "0" level, repeater Fig. 21 will

apply ground over the minus side of the incoming trunk entering selector Fig. 9, passing through contacts of relay D9 to winding of relay K9, upper winding of relay N9, upper winding of relay A9 to free pole of battery. The plus side 80 of the said trunk entering the said selector passes through contacts of relay D9 to lower winding of relay N9, lower winding of relay A9, cam springs to ground. The windings of relay N9 are so connected that when current is flowing 85 through both the electro-magnetic action of each winding will oppose the other. Relay N9 being unbalanced from the fact the minus side of the line is grounded for an appreciable time will actuate. Relays A9 and K9 being in the circuit will 90 actuate and remain actuated so long as current flows through their windings to the trunk. The closing of contacts on relay N9 causes relay E9 to actuate thereby closing a circuit to the rotary magnet which in turn will cause the shaft to be 95 rotated to a non-busy trunk. Upon the off-normal springs being closed ground will be extended through the winding of relay H9, thereby actuating the same for the purpose of excluding the windings of relays K9 and N9 from the 100 trunk circuit. Relay D9 will actuate when the non-busy trunk is seized. The trunk is now extended through contacts on relay G9, private wiper a9 and line wipers b9 to bank contacts, thence to receiving circuit of "long distance" 105 switchboard Fig. 5.

Were the above call to "manual" switchboard in place of to "long distance" switchboard digit "9" would have been pulled on sending device, stepping selector Fig. 26 up to the 9th level and 110 there rotate to a non-busy trunk, thereby extending said call to repeater Fig. 21 where resistance R21 would have been introduced into the minus side of the line leading to the trunk terminating in selector Fig. 9. Upon resistance R21 being 115 introduced in trunk for an appreciable length of time armature of relay K9 will restore to normal position due to reduction of current strength below the value sufficient to hold relay K9 actuated. Upon contacts of relay K9 being closed, ground 120 will be extended from contacts on relay A9 to winding of relay E9, causing same to become actuated for the purpose of rotating shaft to a non-busy trunk which terminates in Fig. 5. Ground is also extended from contacts on relay 125 K9, contacts on relay H9, contacts on relay G9, to upper winding of relay J9, thereby actuating the latter relay for the purpose of extending ground from contacts on relay B9 to the upper winding of relay J9, thereby causing the latter 130 relay to be held in a locked position. Said ground is also extended through contacts on relay H9 to the winding of relay G9, causing the latter relay to become actuated and locked through lower armature of relay J9 for the purpose of 135 switching from private wiper a9 to private wiper c9, and from line wipers b9 to line wipers d9. The call is now extended to receiving circuit Fig. 5 in "manual" switchboard.

Referring to Figs. 25 and 35, making a call 140 from telephone number 591234 to "information" switchboard, telephone number 198, located in the "8" switching center. The call will route from telephone set Fig. 2, to lineswitch Fig. 3, to first selector Fig. 26, to second-third selector 145 Fig. 10, to repeater Fig. 21, to fourth selector Fig. 7, thence to receiving circuit Fig. 5.

Upon calling party removing receiver from hookswitch telephone circuit will be closed over line wires to lineswitch, plunging same in, thus 150

extending line from calling party's telephone to first selector Fig. 26 in the well known manner. Upon the calling party pulling the first digit "1" on sending device, said selector will respond by 5 stepping up to the 1st level and there rotate to a non-busy trunk, thereby extending calling line to second-third selector Fig. 10. Upon calling party pulling digit "9" on sending device shaft of the latter said selector will step up to the 9th level, 10 rotate to the first contact position where private wiper a_{10} will engage first bank contact, which latter contact is permanently grounded. Upon wiper a_{10} engaging said bank contact the said ground will be extended through contacts on relay G10, winding of relay F10, causing the latter relay to become actuated, thereby extending ground from contact on relay B10 to contacts on relay F10 for the purpose of locking it. Ground will now be extended from contacts on relay F10, 15 through off-normal contacts to release magnet, thereby causing the latter to become actuated for the purpose of restoring the shaft to its normal position, at the same time the shaft will incidentally restore off-normal contacts to normal 20 position thereby extending ground from contacts on relay F10 through said off-normal contacts to winding of relay G10, causing it to become actuated, thereby switching private wiper a_{10} to private wiper b_{10} . In this connection it will be 25 noted that when wiper a_{10} engages the said grounded bank contact of the 9th bank level and the armature of the rotary magnet retracts, the relay D10 will actuate, deenergizing relays A10 and B10 in sequence. The latter said relay will 30 sustain until the shaft of the selector restores, whereupon relay D10 will deactivate and cause relays A10 and B10 to reenergize to sustain the armatures of relay B10 attracted. The relay B10 being slow-releasing, will not deactivate under 35 the condition of the latter described functioning. 40 Special sets of bank contacts are connected in multiple and extended to a grounded armature on relay F10. It will be noted from this that with relay F10 in a normal position the groups of bank contacts subject to being swept by wiper a_{10} starting with the second contact will have ground standing on the several bank contacts. If relay F10 be actuated, said ground will be extended 45 through contacts on relay F10 to alternate bank contacts commencing with the first contact. If 50 third digit "8" be now pulled on sending device the shaft will step up to the 8th level and there rotate to a non-busy or non-grounded private contact engageable to wiper a_{10} . The first and 55 each alternate contact being grounded through armature on relay F10 the wiper b_{10} will pass over such grounded contacts as "busy" and select a non-busy alternate contact, commencing with the 60 second contact. The calling party's line is extended to repeater Fig. 21, from one of the alternate contact sets beginning with the second in the 65 8th level. Release trunk No. 2 is extended from private contact of the 8th level corresponding to the line contacts of the trunk seized to winding of relay H21; thence to ground through contacts 70 on relay B21. Relay H21 will now be actuated for the purpose of momentarily grounding the minus side of the line leading from said repeater to Fig. 7. This grounding function has been described before. Upon ground being extended over minus side of line to relay F7, said relay will become unbalanced causing the same to become actuated to the end that the switch will rotate from normal position due to relay E7 being thereby operatively energized, wipers b_7 and d_7 being 75 associated with incoming line. The last said wipers will be rotated by the shaft until private wiper b_7 finds a non-busy trunk to "information" switchboard receiving circuit Fig. 5. The above operation of Fig. 7 was fully described herein- 80 before.

If telephone number 197 were called in lieu of 198, which former number is "complaint" switchboard, the operation will be the same as above described in calling 198 up to calling third digit "7". The operation of Fig. 10 when calling digit "7" is the same as when calling digit "8" above, only that the shaft is stepped up to the 85 7th level in place of the 8th level, thereby extending calling line to repeater Fig. 21. Ground will be extended from contacts on relay B21 through winding of relay N21 over release trunk No. 3, to the seized private bank contact of 7th level of Fig. 10. Relay N21 will now be operated for the purpose of momentarily cutting resistance 90 R21 in series with the minus side of the line. The further operation of this repeater has been previously described. The calling line being extended to Fig. 7 will cause relay G7 to be in a normal position while relay A7 is actuated. As has been 95 previously described this condition will cause the shaft to rotate from normal, with incoming trunk adapted to terminate on private wiper a_7 and line wipers c_7 . The shaft will rotate until private wiper a_7 finds a non-busy trunk in the manner 100 previously described. The trunks not falsely barred accessible to said line wipers c_7 at the 7th level each extend to "complaint" switchboard, receiving circuit Fig. 5.

It is obvious corresponding line contacts of 7th 105 and 8th levels of Fig. 7 as described may lead to the same repeater. For instance, the line bank contacts of the second, or alternate contacts following, of 7th and 8th levels may be in multiple. In such cases companion private No. 2 would run 110 to the corresponding private contact in its respective level and companion private No. 3 would run to the corresponding private contact of its respective level, as shown in Figs. 21 and 21A, with reference to the first contact set. 115

If an extra digit "1" were inserted preliminary to calling the number on the sending device, as by a careless movement of the hookswitch it will in effect make the call "1197" in place of "197". The said preliminary impulse will step selector 120 Fig. 26 up to the 1st level where it will rotate to a non-busy trunk, thereby extending the called line to selector Fig. 10. If first digit "1" be now pulled, shaft of selector Fig. 10 will step up to the 1st level and there rotate to the 1st contact and if same is busy rotate to the 3rd contact and on to the following alternate contacts, since the 2nd and following alternate special private contacts are grounded to armature on relay F10. 125 The trunk which is now selected has access directly or through well known automatic switches to "traffic" switchboard, circuit Fig. 5. The traffic operator will respond knowing the said call was occasioned by a preliminary or extra impulse being introduced. 130

In light of the foregoing paragraph it will be noted that pulling any digit other than "9" or "0" on sending device after single digit "1" has been pulled or introduced, the calling line will 135 be switched into the special circuits to traffic switchboard as described. The switch Fig. 10 guards the system from erroneous calls due to so called preliminary impulses equivalent to the digit "1". 140

- Referring to Figs. 25 and 36, making a call from telephone number 213456 to telephone number 843216. The call will route from telephone set Fig. 2, to the lineswitch Fig. 3, to first selector Fig. 26, to repeater Fig. 21, to lineswitch Fig. 3, to holding circuit Fig. 1, to selector Fig. 26, to holding circuit Fig. 1, to selector Fig. 26, to selector Fig. 26, to connector Fig. 19; thence to called telephone Fig. 2.

Upon calling party removing receiver from hookswitch the circuit will be closed over line wires to lineswitch, plunging the same in, thereby extending calling line to first selector Fig. 26 in the well known manner. Upon calling party pulling first digit "8" said selector will respond by stepping up to the 8th level and there rotate to a non-busy trunk, thereby extending calling line through repeater Fig. 21 to lineswitch Fig. 3, thence to holding circuit Fig. 1 located in "2" switching center, thence over trunk to selector Fig. 26, located in "8" switching center. The operation of holding circuit Fig. 1 and repeater Fig. 21 has been explained hereinbefore in connection with call from 213456 to "long distance" switchboard and also in call 213456 to 843216, using different selectors than in this instance. The three release trunks shown in Fig. 21 are assumed as extending to levels as in Fig. 21A; that is, the "0", "9" and "8" levels. Upon pulling the second digit "4" on sending device selector Fig. 26 will step up to the 4th level and there rotate to a non-busy trunk, thereby extending calling line through holding circuit Fig. 1 to selector Fig. 26, the latter located in "4" sub-office of the "8" switching center. Upon pulling third digit "3" selector Fig. 26 will step up to the 3rd level and there rotate to a non-busy trunk in the well known manner, thereby extending calling line to selector Fig. 26. Upon pulling fourth digit "2" on sending device said selector Fig. 26 will step up to the 2nd level and there rotate to a non-busy trunk, thereby extending calling line to connector Fig. 19, the operation of which is well known, the said connector having access to the bank contacts "16" and there completes the call to the called telephone Fig. 2.

Referring to Fig. 26, relay F26 is in series between the "busy and ground" conductor and the "cam springs". Upon the shaft rotating to the eleventh position the "busy and ground" will be extended through said relay F26, contact springs f26 and e26 to lower winding of relay A26, contacts on relay D26 to the plus side of the line through calling subscriber's telephone back over minus side of line through contacts of relay D26 to upper winding of relay A26. When the foregoing circuit is established the armature of relay F26 will be actuated, thereby causing the meter device G26 to actuate. This meter device will, therefore, register the number of times said selector has moved into the eleventh rotary position because of trunk terminating contacts in any level concerned being busy.

Referring to Figs. 25 and 37, making a call from telephone number 423456 to telephone number 434567. The call will route from telephone set Fig. 2, to lineswitch Fig. 3, to first-third selector Fig. 11, to rotary repeater Fig. 24, to selector Fig. 26, to selector Fig. 11, to selector Fig. 26, to connector Fig. 19; thence to called telephone Fig. 2. The present call is from the same calling telephone to the same called telephone as referred to in Fig. 27. However, an alternative switch path from the line switch is assumed in the present instance.

Upon calling party removing receiver from hookswitch on telephone circuit will be closed over line wires to lineswitch, plunging same in, thus extending line from calling party's telephone to selector Fig. 11. Upon calling party pulling first digit "4" on sending device said selector will respond in the well known manner, stepping up to the 4th level and there rotate to a non-busy trunk, thereby extending calling line to rotary repeater, Fig. 24. Upon calling party pulling the second digit "3" on sending device the shaft of rotary repeater Fig. 24 will operate driven by rotary magnet H24 in unison with shaft of selector Fig. 26, to which the calling line has also been extended from bank contacts of Fig. 11 in multiple with rotary repeater Fig. 24, selector Fig. 26 being operated from the repeating contacts of Fig. 24, and is beyond Fig. 24 at the opposite end of the trunk leading from the right of Fig. 24. Upon selector Fig. 26 stepping up to the 3rd level and there rotating to a non-busy trunk contact shaft of said rotary repeater will coincidentally rotate to the 3rd contact of its bank level and there extend ground from grounded armature on relay G24, over wiper through bank contact, over release wire to first selector banks Fig. 11, thence over wiper a11 and through contacts on relay N11 to winding of relay F11, thereby actuating and locking said latter relay for the purpose of releasing shaft to normal position by means of ground extended from the release trunk, contacts of relays F11, N11, L11, H11 to the release magnet.

The operation of Fig. 24 as regards the rotary element is as follows: When relay A22 retracts consequent to the first open impulse of a digit series being repeated, the rotary magnet H24 will operate to drive wiper R24 and operate the off-normal spring set. Relay G24 will actuate consequent to the primary energization of H24 and remain actuated until after the last impulse of the digit series has transpired, when its lower armature will apply ground to the wiper and engaged bank contact, as set forth. The impulses to H24 will be applied through the upper armature of G24 after the operation of the off-normal springs, but upon a second series of impulses ensuing the rotary magnet R24 will not be energized since the off-normal springs have operated, which also prevents relay G24 from operating.

Upon shaft of Fig. 11 being returned to normal position off-normal contacts are opened causing relay H11 to be deenergized. Ground will now be extended from contacts on relay F11, through contacts on relay H11 to winding of relay N11, causing said relay to be actuated and remain so during the further movement of the shaft due to locking circuit through its own contacts, contacts of F11, and contacts of B11 to ground. Incidental to the operation of relay N11, release trunk will be switched from private wiper c11 to private wiper e11 and line wires will be switched from line wipers d11 to line wipers f11. Selector Fig. 11 is now in a condition to receive the third digit "4", which upon being pulled on sending device steps the shaft to the 4th level and there rotates to a non-busy trunk, thereby extending calling line over private wiper e11 and line wipers f11, through bank contacts to a local selector Fig. 26. Upon fourth digit "5" being pulled on sending device the shaft of Fig. 26 will step up to the 5th level and there rotate to a non-busy trunk, thereby extending calling line to connector Fig. 19, the operation of which is well known, the said connector having access to bank contacts "67" 150

and there completes the call to the called telephone Fig. 2.

Should telephone number 424567 have been called in place of 434567 the shaft of selector Fig. 11 would have been stepped up to the 4th level and there rotated to a non-busy trunk, thereby extending the calling line to rotary repeater Fig. 24 and also to selector Fig. 26 through repeater Fig. 24 as before described. Upon pulling second digit "2" on sending device selector Fig. 26 would step up to the second level and there rotate to a non-busy trunk. Rotary repeater Fig. 24 being in the circuit would rotate in unison with the selector Fig. 26 to the 2nd bank contact, thereby extending ground from armature on relay G24 through wiper k24, over bank contact and release wire to bank contact of selector Fig. 11, thence over wiper b11 through contacts on relay L11 to winding of relay G11, thereby actuating said latter relay for the purpose of releasing shaft of selector Fig. 11 to normal by means of ground extended from the release trunk, contacts on relays G11, N11, L11, H11 to the release magnet. Upon shaft of selector Fig. 11 being restored to normal position off-normal contacts thereon are opened thereby causing relay H11 to be deenergized. Ground will now be extended from contacts on relay G11 through contacts on relay H11 to winding of relay L11, causing the latter relay to be actuated and remain so during further movement of shaft due to locking circuit through its own contacts, contacts of G11, to the release trunk.

Incidental to the operation of relay L11 the release trunk will be switched from private wiper c11 to private wiper g11 and line wires will be switched from line wipers d11 to line wipers h11. Selector Fig. 11 is now in condition to receive the third digit "4" which upon being pulled on sending device steps the shaft to the 4th level and there rotates to a non-busy trunk, thereby extending calling line over private wiper g11 and line wipers h11, through bank contacts to selector Fig. 26. Upon fourth digit "5" being pulled on sending device the shaft of selector Fig. 26 will step up to the 5th level and there rotate to a non-busy trunk, thereby extending calling line to Fig. 19, the operation of which is well known. The said connector having access to bank contacts "67" and there completes the call to the called telephone Fig. 2.

Referring to Figs. 25 and 38, making a call from telephone number 213456 to telephone number 34567. The call will route from telephone set Fig. 2, to lineswitch Fig. 3, to first selector Fig. 26, to repeater Fig. 21, to selector Fig. 23, to selector Fig. 13, to connector Fig. 19; thence to called telephone Fig. 2.

Upon calling party removing receiver from hookswitch circuit will be closed over line wires to lineswitch, plunging same in, in the well known manner, thus extending line to first selector Fig. 26. Upon pulling first digit "3" on sending device shaft of said selector will step up to the 3rd level and there rotate to a non-busy trunk, extending call to repeater Fig. 21, located in the "2" switching center. Said call is thus extended through said Fig. 21 to selector Fig. 23, the latter located in the "3" switching center. Upon calling party pulling second digit "4" on sending device shaft of selector Fig. 23 will respond by stepping up to the 4th level and there rotate to a non-busy trunk, thereby extending call to selector Fig. 13. Upon pulling the third digit "5" the shaft of selector Fig. 13 will re-

spond by stepping to the 5th level and there rotate to a non-busy trunk, thereby extending calling line to connector Fig. 19, the operation of which is well known, the said connector having access to bank contacts "67" and there completes the call to called telephone Fig. 2.

Should the call have been from telephone number 213456 to telephone number 35621 the operation of the switches would have been the same up to selector Fig. 23, said Fig. 23 having line wipers, one private wiper and a special wiper a23, the latter for the purpose of extending ground from contacts on relay D23 over said wiper, through bank contacts to selector Fig. 13, for the purpose of operating relay F13 over conductor designated "S. W. WIRE". The 4th level of said selector Fig. 23 does not extend ground from special wiper a23 to selector Fig. 13. Therefore, after selector Fig. 23 has operated by stepping to the 5th level and there rotates to a non-busy trunk the selector Fig. 13 terminating the trunk will be in a condition to receive the third digit. Upon pulling the third digit "6" on sending device the shaft of selector Fig. 13 will step up to the 6th level and there rotate to a non-busy trunk extending the lines and release trunk through contacts of relay F13 to private wiper c13 and line wiper d13, thence through bank contacts to connector Fig. 19, the operation of which is well known, the said connector having access to bank contacts "21" and there completes the call to called telephone Fig. 2.

Referring to Figs. 25 and 39, making a call from telephone number 293263 to telephone number 293476. The call will route from telephone set Fig. 2, to lineswitch Fig. 3 (eliminating fourth selector in a branch Fig. 22) to secondary lineswitch Fig. 4, to repeater Fig. 21, to selector Fig. 26, to selector Fig. 23, back to eliminating fourth selector Fig. 22, to connector Fig. 19; thence to called telephone Fig. 2.

Upon calling party removing receiver from hookswitch the circuit will be closed over line wires to lineswitch, plunging the same in to extend the connection to secondary lineswitch Fig. 4, and also to eliminating selector Fig. 22 in the branch. Following the call through the regular selectors, secondary lineswitch Fig. 4 will select an idle repeater Fig. 21 and associated trunk to the branch office where said trunk terminates in a selector Fig. 26. Upon pulling the first digit "2" on sending device first selector Fig. 26 will respond by stepping up to the 2nd level and there rotate to a non-busy trunk in the well known manner, thereby extending calling line to second selector Fig. 26. If second digit "8" be now pulled on sending device the shaft of said second selector will step up to the 9th level and there rotate to a non-busy trunk, thereby extending calling line to third selector Fig. 26. Upon the third digit "3" being pulled on sending device shaft of said third selector will step up to the 3rd level and there rotate to a non-busy trunk. There will be no further operation of selectors due to the fact that eliminating fourth selector Fig. 22 has operated in response to the first three said pulling of the digits in unison with the respective selectors described above.

Referring to the operation of Fig. 22 it is as follows:

Upon digit "2" being pulled on sending device the shaft will rotate to the 2nd contact set. Ground will be extended from contacts on relay E22, contacts on relay F22, upper winding of relay K22, contacts on relays C22 and L22, over

- wiper a_{22} , through its engaging bank contact to contacts on relay G22, thence through winding of said relay G22. The circuit described having passed through the windings of relay K22 and relay G22 will cause both said relays to become actuated; relay G22 remaining actuated during the further rotary movements of the switch by reason of locking to ground on lower contact of relay F22. Upon relay K22 being actuated and locked through lower contact of relay C22 ground will be extended from the release trunk, through contacts on relay C22, contacts on relay K22, off-normal contacts, to the winding of release magnet, causing the same to become actuated for the purpose of returning the shaft to the normal position. Upon second digit "9" being pulled on sending device relay C22 will actuate and unlock relay K22 and the shaft of Fig. 22 will rotate in to the 9th contact set.
- 20 The circuit as above described may be traced from contacts on relay B22, contacts on relay F22, upper winding of relay K22, contacts on relays C22 and L22, wiper a_{22} , thence through bank contact, contacts on relay G22 to contact on relay H22, thence to winding of said relay H22. Upon the circuit being closed between the windings of relays H22 and K22 they will become actuated, relay H22 remaining so during the further rotary movement of shaft. Upon relay K22 becoming actuated the circuit will be closed from contacts on relay B22 to release magnet through the several contacts as described above, causing the said release magnet to become actuated for the purpose of restoring its shaft to normal. Upon the third digit "3" being pulled on sending device the shaft will rotate to the 3rd bank contact and there extend ground from contacts on relay B22 over wiper a_{22} , through bank contact to contact on relay H22 (K22 having unlocked consequent to the first impulse of digit "3"), thence to winding of relay J22. Upon the latter circuit being closed between relay J22 and relay K22 said relays will become actuated, relay J22 remaining so during the further rotary movement of the switch Fig. 22. Upon the actuation of relay K22 ground will be closed from relay B22 to the winding of the release magnet, causing the same to be actuated for the purpose of releasing shaft of Fig. 22.
- 50 Upon the shaft being restored to its normal position, ground will be extended from contacts on relay F22, contacts on relay J22, off-normal contacts to winding of relay F22, thereby causing said relay F22 to become actuated and remain so by means of ground extended from relay B22, contacts on relay F22, thence to winding of relay F22. Upon the operation of relay F22 relays J22, H22 and G22 will be restored to their normal positions respectively, by reason of ground being open through contacts on said relay F22 to the windings of the said relays. The upper armature of relay F22 is adjusted to make before the lower armature attracts from its resting grounded contact.
- 65 Upon the operation of the relay F22, to all intents and purposes Fig. 22 will become a standard first selector (as Fig. 26) as regards circuits and action.
- 70 Should the call have been to telephone number 294476 in lieu of telephone number 293476 the operation of eliminating selector Fig. 22 would have been the same as described up to the third digit "4", which upon being pulled on sending device will cause relay K22 to unlock and the shaft in Fig. 22 to rotate in to the 4th bank contact.

The circuit as before described may be traced from contacts on relay B22 through contacts on relay F22, upper winding of relay K22, contacts on relays C22 and L22, over wiper a_{22} , thence through contacts on relay H22 to winding of relay N22, causing said relay N22 to be actuated and locked to the lower armature of relay F22, for the purpose of extending ground to the winding of relay J22 to lock said relay J22 to the lower armature of relay F22. Upon relay J22 becoming actuated ground will be extended from the contacts of said relay J22, contacts of relay N22, thence to winding of relay L22, causing the latter to be actuated for the purpose of switching the private conductor from private wiper a_{22} to private wiper b_{22} and from line wipers c_{22} to line wipers d_{22} . Incidental to the closing of contacts on relay L22 locking ground will be extended from the release trunk to the winding of said relay L22, causing the said relay to remain actuated until the calling party releases the call.

Upon the circuit being closed including windings of relays N22 and K22 said relays will become actuated. Upon the actuation of relay K22 ground will be closed from contacts on relay B22 to the winding of the release magnet causing the same to become actuated for the purpose of releasing shaft of Fig. 22 and relay K22 to their normal positions respectively. Upon the shaft being restored to its normal position ground will be extended from grounded armature on relay F22, through contacts on relay J22, off-normal contacts, to winding of relay F22, thereby causing said relay F22 to become locked to contacts on relay B22. Upon the operation of relay F22 relays N22, J22, H22 and G22 will be restored to their normal positions respectively, by reason of ground being disconnected at lower armature of relay F22. Upon the operation of relay F22, to all intents and purposes Fig. 22 will become a standard selector (as Fig. 26) as regards circuits and action. Relay K22 will unlock upon the first impulse being sent effective to relay C22, or upon the calling party replacing the receiver. The further process of the call will be the same as in the former call to be further described.

When Fig. 22 functions as a selector it has access to one of two selector groups through the lower bank and its companion private in upper bank and through middle bank and its companion private in upper bank respectively depending upon wipers in circuit.

Should any other digits than mentioned with reference to Fig. 22, or digits in other succession than those mentioned, have been pulled on sending device, the circuit to relay F22 would have been closed to ground through cam springs X22, which are operated by cam Z22, Fig. 22A, at all off normal positions of the shaft at the normal level for the purpose of actuating relay D22. The latter relay upon actuation switches the plus and minus lines from the windings of relay A22 to line wipers C22; said line wipers not engaging bank contacts will leave the minus and plus lines open, thus disassociating the transmission limbs of said Fig. 22; the said Fig. 22 being thereafter inoperative until calling party releases connection to called party, restoring the circuits to normal position.

It will be noted, in this connection, that if relay F22 is caused to actuate from the cam springs X22, whereby said F22 is locked actuated through contacts on relay B22, and wherein relay D22 actuates forthwith as set forth, the relay F22 will be sustained actuated from ground on

- lower armature on relay A22, lower armature on relay D22 to the winding of relay F22 before the upper armature of relay B22 has had time to retract, due to its slow-release characteristic.
- 5 All the bank contacts shown in Fig. 22B engageable to wiper a22, excepting the second (representing the first digit of a number which may be reached through the banks of Fig. 22) are open. That is, if any other digit than "2" is sent first, the relay F22 will then be energized through the contact set X22 because relay K22 will not actuate due to all extensions from the connected bank contacts shown in Fig. 22B leading to open relay contacts normally. When the first digit sent causes relay G22 to actuate, the ninth bank contact is thereby extended to the winding of relay H22. When the second digit sent causes relay H22 to actuate, the third bank contact in Fig. 22B is thereby extended to the winding of relay J22 and the fourth bank contact in Fig. 22B is thereby extended to the winding of relay N22 as well. Thus, if wiper a22 does not complete an operative circuit on an engaged bank contact in Fig. 22B, upon relay C22 deactuating, the relay K22 will remain inert so the circuit from the release trunk can be completed through spring set X22 as has been set forth. In this connection, it is to be noted that the upper winding of relay K22 is of such low resistance (or of such adjustment) as compared to the winding of relay D22 and the windings of relays G22, H22, J22 and N22 that when the upper winding of relay K22 is energized in multiple with the windings of a said relay and relay D22, the winding of the latter relay will not attract its armatures operatively.
- Upon fourth digit "4" being pulled on sending device the shaft of Fig. 22 will step up to the 4th level and there rotate to a non-busy trunk. Incidental to the stepping up of the said shaft the holding circuit to the secondary lineswitch Fig. 4 will be opened due to the vertical off-normal contacts opening, causing the said secondary lineswitch to restore to its normal position, incidentally releasing the said three selectors Fig. 26 beyond said secondary lineswitch.
- The call being now extended to the connector Fig. 19, the operation of which is well known the said connector having access to the bank contacts "76" there completes the call to the called telephone Fig. 2.
- Referring to Figs. 25 and 40, making a call from telephone number 843216 to telephone number 651634. The call will route from telephone set Fig. 2, to lineswitch Fig. 3, to first selector Fig. 26, to repeater Fig. 21, to selector Fig. 6, to selector Fig. 26, to selector Fig. 23, to connector Fig. 20; thence to called telephone Fig. 2.
- Upon calling party removing receiver from hook-switch circuit will be closed over line wires to lineswitch plunging same in, in the well known manner, thereby extending calling line to the first selector Fig. 26. Upon pulling first digit "6" on sending device said first selector will step up to the 6th level and there rotate to a non-busy trunk thereby extending calling line to repeater Fig. 21 and through said Fig. 21, to selector Fig. 6. Upon pulling the second digit "5" on sending device selector Fig. 6 will respond by stepping up to the 5th level and there rotate to a non-busy trunk, thereby extending said calling line to the "5" sub-office of the "6" switching center, terminating in selector Fig. 26.
- Referring to Fig. 6, tracing the minus side of the line to the line wiper b6 it will be noted that the multiplied windings of relay F6 are inserted in series. The plus line is extended to line wiper c6. Upon line wipers b6 and c6 engaging a non-busy trunk current will flow from selector Fig. 26 over the trunk to bank contacts of Fig. 6, thence through line wipers b6 and c6; the b6 line wiper being in the minus side of the line will have relay F6 in series. Upon current flowing through relay F6, said relay will be actuated for the purpose of closing ground through its contacts to the winding of relay H6, thereby closing ground through its contact, thence to private wiper a6 for the purpose of guarding trunk selected by this same selector. Ground from contacts on relay H6 is also extended through contacts on relay D6, cam springs, winding of relay D6, rotary magnet springs, through off-normal contacts to winding of relay E6. Relay H6 having a retarded release will not restore to normal while dialing impulses are being transmitted over line wires from calling telephone to selector Fig. 26. Relay F6 being in series with the minus side of the line will operate in unison with the dial impulses transmitted to Fig. 26 and will also restore to normal position upon current flow ceasing at the instant of reversal in the connector upon called party responding. During the short intervals, wherein the armature on relay F6 is retracted contact on relay H6, the latter relay having a retarded release characteristic, will remain closed long enough to guard the private.
- The call being now extended to selector Fig. 26, said selector Fig. 26 will be in a condition to receive the third digit "1", which upon being pulled on sending device will step its shaft up to the 1st level and there rotate to a non-busy trunk, thereby extending calling line over the private wiper a26 and line wipers b26, thence through bank contacts to selector Fig. 23. Upon the forth digit "6" being pulled on sending device the shaft of said selector will step up to the 6th level and there rotate to a non-busy trunk contact, extending the calling line to connector Fig. 20. Upon private wiper of selector Fig. 23 selecting a non-busy trunk contact ground will be extended from contacts on relay D23 over wiper a23, through bank contacts to relay J20, thereby actuating the said relay for the purpose of switching from private wiper a20 to private wiper c20, and from line wipers b20 to line wipers d20. Upon the last two digits "3" and "4" being pulled on sending device the shaft of said connector Fig. 20 will step up to the 3rd level and rotate in to the 4th contact thereby extending the said call through line wipers d20 and private wiper c20 to the desired bank number; thence to called telephone Fig. 2.
- If number 651134 had been called in lieu of 651634 the call would have been extended through the several switches to selector Fig. 23 in the same manner as described. Upon pulling the fourth digit "1", the said selector Fig. 23 will step up to the 1st level and there rotate to a non-busy trunk thereby extending calling line to connector Fig. 20. Ground will be extended from contacts on relay D23 through wiper a23 to bank contact of said selector Fig. 23. There being no connection between this bank contact and connector Fig. 20, said ground described will terminate at the dead bank contact of selector Fig. 23. The call being now extended to connector Fig. 20. The operation responsive to pulling the last two digits will be the same as previously described, but with the difference that the call will be extended over private wiper a20

and line wipers b_{20} to bank terminals "34" of the "1" hundred, in lieu of the "6" hundred.

Referring to Figs. 6 and 6A, relay D6 and D6' have extra contacts, d_6 and d_6' respectively, for the purpose of extending ground in series through certain groups of selector switches to relay N6, Fig. 6B. The object of extending this ground as above is to operate register device G26, Fig. 6B, through the agency of relay N6. Figs. 6 and 6A are the first and last selectors respectively of a said group of switches.

Contact e_6 shows an intermediate selector switch contact corresponding to contacts designated d_6 and d_6' , it being noted that contact e_6 is a series contact only serving to open circuit between first and last selector of group. Thus in order to complete the circuit between relays D6 and N6 all selector switches to which Fig. 6B is connected must be busy.

Referring to Figs. 25 and 41, making a call from telephone Number 843216 to telephone number 634567. The call will route from telephone set Fig. 2, to the lineswitch Fig. 3, to first selector Fig. 26, to repeater Fig. 21, to second-third selector Fig. 15, to fourth selector Fig. 26, to connector Fig. 19; thence to called telephone Fig. 2.

Upon calling party removing the receiver from hook-switch on telephone the circuit will be closed over line wires to line switch plunging same in, thereby extending calling line to first selector Fig. 26, in the well known manner. Upon calling party pulling the digit "6" on sending device said selector will step up to the 6th level and there rotate to a non-busy trunk, thereby extending calling line to repeater Fig. 21. The operation of said repeater in this call does not include special functions as described, relating to grounding of minus trunk or including resistance in minus trunk through the agency of relays G21, H21 and N21, its operation in this case, therefore, being normal and as well known.

The call being now extended to second-third selector Fig. 15. Upon second digit "3" being pulled on sending device second-third selector Fig. 15 will step up to the 3rd level and rotate to first set of contacts where current will be extended from free terminal of relay E15 through contacts on relay H15, contacts on rotary magnet, contacts on relay D15, contacts on relay N15, contacts on relay J15, wiper a_{15} , bank contact, contacts on relay N15, lower winding of relay G15 to ground, thereby causing said relay to actuate, locking said relay G15 by means of ground extended from contacts on relay B15. Said ground also operates release magnet through contacts on relay G15, contacts on relay N15, contacts on relay J15, contacts on relay H15; thence to release magnet. Upon shaft of Fig. 15 returning to normal position off-normal springs are open, allowing relay H15 to de-energize, thereby extending ground from contacts on relay G15, through contacts on relay H15, to winding of relay N15, causing the same to be actuated and locked to contact on relay B15 for the purpose of switching from private wiper a_{15} to private wiper b_{15} and line wipers c_{15} to line wiper d_{15} . Upon third digit "4" being pulled on sending device the shaft of Fig. 15 will step up to the 4th level and there rotate to a non-busy trunk, thereby extending calling line to fourth selector Fig. 26.

If fourth digit "5" be now pulled on sending device the shaft in Fig. 26 will step up to the 5th level and there rotate to a non-busy trunk, thereby extending calling line to connector Fig. 19, the

operation of which is well known, the said connector having access to bank contacts "67" and there completes the call to the called telephone Fig. 2.

If the call had been to telephone number 623456 in lieu of 634567 as just described, selector Fig. 15, would be operated as follows: Upon its shaft being stepped up to the 2nd level and rotated to first contact set current would be extended from winding of relay E15 to wiper a_{15} as before described, bank contact, contacts on relay J15 to lower winding of relay F15 to ground, causing said relay to become actuated locking itself by means of ground extended from contacts on relay B15 through contacts on relay F15 to upper winding of said relay F15. Said ground is also extended through contacts on relay N15, contacts on relay J15, contacts on relay H15 to release magnet. Upon shaft returning to normal position off-normal contacts are opened which causes relay H15 to de-energize, thereby extending said ground from contacts on relay F15 through contacts on relay H15 to winding on relay J15, causing the latter relay to be actuated for the purpose of switching from private wiper a_{15} to private wiper b_{15} and line wipers c_{15} to line wipers d_{15} . Upon fourth digit "3" being pulled on sending device the shaft of selector Fig. 15 will step up to the 3rd level and there rotate to a non-busy trunk, thereby extending calling line to selector Fig. 26. If digit "4" be now pulled on sending device shaft of selector Fig. 26 will respond by stepping up to the 4th level and there rotate to a non-busy trunk, thereby extending called line to connector Fig. 19, the operation of which is well known, said connector having access to the bank contacts "56" and there completes the call to the called telephone, Fig. 2.

Those skilled in the art to which my invention belongs will be able to apply it as an amplification or in part only without departing from its scope.

When in the appended claims the term "wiper set" is used, what is meant is an operative group of wipers, for example, in Fig. 20, wipers a_{20} and b_{20} is a wiper set, and c_{20} and d_{20} is a set. Also when in the subjoined claims the term "bank level" is used, what is meant is the certain numerical vertical position of a row of bank contacts of the switch, rather than a specific level. That is to say, the switch may have two sets of wipers (as in Fig. 20), each set cooperating with a certain group of bank contacts in rows, and in that case, the reference to the fifth level, for example, would refer to rows of bank contacts engaged by either or both sets of wipers at the fifth vertical position.

I claim.—

1. A selector having a plurality of bank contact levels, a wiper set normally opposite one level, and means for moving the wiper set directly into the normal level or first directly opposite to and then into any other levels.

2. A selector having a plurality of bank contact levels, a wiper set normally opposite one level, means for moving the wiper set into engagements with the contacts of the normal level or first in one direction to any other level directly followed by movement in a second direction into engagement with contacts of the selected level.

3. A selector having a plurality of bank contact levels, a wiper set normally opposite one level, means for effecting an automatic selective movement of the wiper set into engagements with the contacts of the normal level or first by a directive movement in one direction to any other level fol-

- lowed by movement in a second direction into engagement with contacts of the selected level.
4. A selector having eleven sets of bank levels with a set of bank contact engaging wipers, ten of which levels correspond to off-normal vertical steps, one level aligning with the normal position of said bank wipers, means for directly moving said wiper set off-normal to a desired level and thereafter into engagement with a contact set in the said desired level, and means for causing the wiper set to move directly into engagement with the level with which the wipers normally align wherein step-by-step movement is not directly effected.
5. A selector having a contact bank and wiper set, a shaft with a normal rotary movement in which the bank contact wiper set registers with bank contacts of a normal level, a line relay, an auxiliary relay associated in circuit relation with the windings of the line relay which will actuate upon a predetermined unbalanced line condition ensuing; the actuation of said auxiliary relay causing said shaft to start rotating from normal position, and means for moving the wiper set into engagement with bank contacts in any other level.
6. A selector having a plurality of bank contact levels, wiper sets normally opposite a corresponding number of normal levels, means for moving the wiper sets into engagement with the normal levels and selecting the desired wiper set, or moving one of the wiper sets opposite to and then into one of the other levels.
7. A telephone system comprising a telephone line, a selector switch connected with said line, said selector having a plurality of bank contact levels and a cooperating wiper set normally opposite one of the levels, and means controlled from a station on said line for effecting a travel over the normal level or directly to any other level, and then to a contact in the selected level.
8. In a telephone system, a selector, the said selector having two sets of wipers, a level of bank contact sets normally in selective alignment with said sets of wipers respectively, another level of bank contact sets, means for causing the selector to at will selectively hunt with respect to one or the other of said wiper sets and its specific aligned contact sets, and means for directly setting one of said wiper sets into alignment with said another level of bank contact sets and for then hunting thereon.
9. A telephone system comprising a selector switch having a plurality of bank contact levels, a wiper set normally opposite one level, means for moving the wiper set directly into the normal level or first opposite to and then into any other level, another selector having access to the first said selector so as to effect different circuit changes, and means whereby the circuit change effected determines the movement of the first said selector.
10. A selector having a wiper and shaft, a contact set operative from a cam secured to shaft of said selector; a release wire, a release magnet, a preceding selector; said cam adapted to engage and close said contact from a predetermined level position, the closing of said contact serving to ground the release wire so as to operate the release magnet of the preceding selector over a bank contact and companion wiper on said preceding selector, for the purpose of releasing both said selector shafts to normal position.
11. A second selector switch having a wiper and shaft, contact sets operative from a cam secured to the shaft of said selector; said cam adapted to engage and close said contacts from two level positions respectively; a release wire, a release magnet, a preceding selector, the closing of said contacts serving to ground the release wire so as to operate the release magnet over bank contacts and companion wiper on the first selector preceding for the purpose of releasing both said selector shafts to normal position and at the same time switch the line conductors of said preceding selector from one set of wipers to a second set of wipers; a fourth selector, said second set of wipers having access to bank contacts extending to said fourth selector, itself lastly functioning as a third selector.
12. A selector having two normal levels; line and private wipers, an incoming line, each said level accessible from companion wiper sets, both said wiper sets not being associated with circuits simultaneously, a line relay, a second relay, a relay associated with the line relay adapted to actuate upon a predetermined unbalanced line condition ensuing, said actuation causing said second relay to actuate with the line relay; said actuation starting the selector shaft into rotary movement and co-incidently switching corresponding private and line wipers into circuit relation with reference to the incoming line and normal levels of the outgoing trunks; a third relay associated with the line relay adapted to actuate upon resistance being included in the incoming line; said latter relay starting the selector shaft into selective rotary movement, the wipers accessible to one of said normal levels of bank contacts being in normal circuit relation with respect to the incoming line.
13. A telephone system comprising a telephone line, a coordinate movement automatic switch connected to the line, wipers for the switch and a plurality of bank contact levels one of which is a normal level, a calling device at a station on the line for operating the switch wipers to connect with the off-normal levels, and a switch contact for introducing an abnormal line condition so as to operate the wipers to move over the normal level.
14. In a telephone system a subscriber's station, a coordinate movement selector having normal and offnormal levels, a wiper for engagement with all of the levels, a line extending to a differential relay of the selector, means at said subscriber's station for introducing temporary ground on said line for the purpose of deriving unbalanced current strength through said relay to cause it to close an auxiliary circuit so as to operate said wiper to rotate directly from its normal position over the normal level.
15. In a telephone system a subscriber's station, a coordinate movement selector having normal and offnormal levels, a wiper for engagement with all of the levels, a line extending to a differential relay of the selector, means at said subscriber's station for introducing temporary ground upon said line, said ground deriving unbalanced current strength through said relay causing it to actuate and thereby close an auxiliary circuit so as to operate said wiper to rotate directly from its normal position into selective relation to the normal level contacts, trunks extending from said contacts, said trunks terminating in a receiving circuit adapted to project current serially to said subscriber's station and incidentally introduce a holding condition into said selector until said serial condition is broken by said subscriber's station circuit becoming opened.
16. A telephone system comprising a telephone line and station, a relay, an automatic switch

- connected with said line and having a normal and also off-normal levels, a wiper set opposite the normal level, a calling device at the station for moving the wiper set to the off-normal levels, 5 means for operating said relay, and a switch contact at said station for introducing a resistance in the line circuit so as to deactivate said relay to cause the wiper set to move over the normal level.
- 10 17. A telephone system comprising a telephone line and station, a relay, an automatic switch connected with said line and having a normal and also off-normal level, a wiper set opposite the normal level, a calling device at the station for moving the wiper set to the off-normal levels, 15 means for operating said relay, and a switch contact at said station for temporarily introducing a resistance in the line circuit so as to deactivate said relay to cause the wiper set to move over the normal level.
17. A telephone system comprising a telephone line and station, a relay, an automatic switch connected with said line and having a normal and also off-normal levels, a wiper set opposite the normal level, a calling device at the station for moving the wiper set to the off-normal levels, 20 means for operating said relay, and a switch contact at said station for connecting ground to the line effective to the relay to cause the wiper set to move over the normal level.
- 25 18. A telephone system comprising a telephone line and station, a relay, an automatic switch connected with said line and having a normal and also off-normal levels, a wiper set opposite the normal level, a calling device at the station for moving the wiper set to the off-normal levels, and a switch contact at said station for connecting ground to the line effective to the relay to cause the wiper set to move over the normal level.
- 30 19. In a telephone system, a coordinate movement selector having levels of bank contacts and alternative wiper sets, one set of wipers being normally associated, said contacts terminating outgoing trunks, an auxiliary wiper carried by 35 the shaft of said selector which is adapted to engage a contact corresponding to one of said levels, a release circuit, said contact completing the release circuit for the purpose of restoring said shaft to normal position and incidentally adapt alternative wipers of said selector to electrically 40 register with a second set of outgoing trunk contacts, and means to operate the switch so the auxiliary wiper will engage the said contact corresponding to one of the said levels.
- 45 20. In a telephone system, a repeater circuit, an automatic switch at the outgoing end of said circuit, a second automatic switch for connection with the incoming end of said circuit, and means for automatically connecting ground to the outgoing end of said circuit to operate said first switch upon seizure of the repeater circuit.
- 50 21. In a telephone system, a repeater circuit, an automatic switch at the outgoing end of said circuit, a second automatic switch for connection with the incoming end of said circuit, and means for automatically connecting a resistance in circuit with the outgoing end of said circuit to operate said first switch upon seizure of the repeater circuit.
- 55 22. In a telephone system, a repeater circuit, an automatic switch at the outgoing end of said circuit, means whereby said switch is differently operable by a ground or a resistance connection 60 from the repeater circuit, a second automatic switch for connection with the incoming end of said repeater circuit over alternative paths, and means for connecting ground or resistance from the repeater circuit upon seizure thereof according to the path over which connection is made.
- 65 23. In a telephone system, line bank contacts in multiple relation to a repeater, companion private bank contacts respectively associated with said line bank contacts, a selector accessible 70 to said contacts by means of its wipers, the said
- private bank contacts having conductors leading independently from said private bank contacts to a common release trunk in said repeater, one of said conductors including a relay adapted to temporarily introduce a grounded condition on transmission conductors leading from said repeater, a second of said conductors leading from said private bank contacts likewise including a relay adapted to temporarily introduce an auxiliary resistance into said transmission conductors leading therefrom.
- 80 24. In a telephone system, line bank contacts in multiple relation to a repeater, companion private bank contacts respectively associated with said line bank contacts, a selector in access to said contacts by means of its wipers, the said private bank contacts having conductors leading independently from said private bank contacts to a common release trunk in said repeater, one of said conductors including a relay adapted to temporarily introduce a grounded condition on transmission conductors leading from said repeater, said conductors leading to a selector having a normal level, said selector adapted to rotate from a normal position upon said ground being applied for the purpose of selecting companion idle trunk contacts on said normal level.
- 85 25. In a telephone system, a wiper selector having a normal restored position for its wipers, the said selector having two level bank contact groups, a wiper set specific for each level, the bank contacts of each said level being connected to a trunk group respectively, and means for at will operating the sets of wipers with hunting relation to one or the other of the said level sets 90 of bank contacts directly from their normal position.
- 95 26. A selector with a trunk leading from a bank level to a second selector, a second trunk leading from said level to a third selector, means controllable from a contact made by the first said selector rotating at a predetermined level to determine which said trunk may be seizable.
- 100 27. In a telephone system, a calling line, called lines, a sending device on the calling line for sending a digit series at each operation thereof, a primary switch, primary trunks of two different numerical orders, each said trunk leading from the primary switch to a secondary switch of corresponding numerical order, a secondary trunk link leading from the said secondary switches respectively, other secondary trunk links for further extending a connection toward a called line, means for operating the primary switch directly responsive to the calling device to extend 105 the calling line over a primary trunk of one or the other said orders in the direction of one or another of said called lines respectively, and means responsive to one predetermined number of directive operations of the calling device for extending the call from the calling line to any said called line called, said means being operated to include a different number of secondary trunk links between the said primary switch and the 110 line called according to the numerical order to which the trunk used in the extension leading from the said primary switch belongs.
- 115 28. In a telephone system, a calling line, a calling device on the calling line, called lines respectively reached by operating the calling device an equal number of times, a switch which will be set to operate as a selector of one numerical order responsive to the first operation of the calling device to attain connection with a trunk of a first 120
- 125
- 130
- 135
- 140
- 145
- 150

one of said groups in the direction of one said called line and alternatively as a selector of another numerical order responsive to the second operation of the calling device to attain connection with a trunk of a second one of said groups in the direction of another said called line, a relay for changing the switch to operate as a switch of the said another order, means responsive to specific operation of the calling device for setting the switch into hunting relation with the trunks of said one numerical order, means responsive to a different specific operation of the calling device effective to operate the relay, and means responsive to the calling device after the relay has been operated to set the switch into hunting relation with the trunks of the said another numerical order.

29. In a telephone system, a switch normally functioning as a repeater and having a step-by-step movable member operating in one plane only, which is movable responsive to the first series of impulses applied to said switch, and means controlled by said member for releasing the switch responsive to a predetermined number of impulses being transmitted thereto.

30. In a telephone system, a switch normally functioning as a repeater and having a step-by-step movable member, which is movable responsive to the first series of impulses applied to said switch, and means controlled by said member for releasing the switch responsive to a predetermined number of impulses being transmitted to said member so as to render the movable member of the switch unresponsive to subsequent impulses.

31. A repeater having a step-by-step element movable responsive to the impulses actuating said repeater, a preceding selector, a release circuit in the selector extended to the repeater, said element adapted to complete a circuit to the said release circuit and to an associated selector preceding for the purpose of releasing said selector and said element to normal positions respectively upon said element stepping to a predetermined position and means for transmitting impulses to actuate the repeater.

32. In a telephone system, a calling line, a sending device on the calling line, an interposed impulse repeater, a selective linking switch preceding and a selective switch succeeding said repeater, said repeater having a step-by-step element movably responsive to the impulses sent from the calling line to actuate the said succeeding switch, a release circuit for restoring the said preceding switch, and means whereby when the said step-by-step element steps to a predetermined position the release circuit will be made operative to disconnect the said preceding switch from the repeater whereby the connection through the preceding switch and including the link having the interposed repeater will be destroyed.

33. A repeater having a step-by-step element movably responsive to the impulses actuating said repeater, a preceding selector, said element adapted to complete a circuit to the associated selector preceding for the purpose of releasing said selector and said element to normal positions respectively upon said element moving step-by-step to a predetermined position; said element performing no effective function if any other position than that predetermined is reached.

34. In a telephone system, a wiper switch having a relay, a cooperating preceding selector with

an auxiliary wiper adapted to complete a circuit from the said relay in the said switch over an auxiliary contact accessible to said auxiliary wiper, the completing of said circuit causing the actuation of said relay for the purpose of switching sets of alternative wipers of the succeeding switch accessible through bank contacts thereof.

35. In a selector a first relay in series with one of its outgoing transmission limbs, a second relay in a local circuit of said first relay, said second relay carrying contacts the closing of which secures said selector against release, said second relay having a retarded release characteristic for the purpose of maintaining said contacts closed during an opening of short duration of contacts on said first relay.

36. A switch having a normal rotary movement responsive to a first series of impulses applied thereto, a first set of wipers carried by a shaft of said switch accessible to a normal level, a second set of wipers carried by said shaft accessible to a selector bank, said first wipers successively passing over said contacts in response to predetermined successive series of impulses corresponding to digits of a called number and releasing to normal position at the termination of each said series of impulses, predetermined contacts conductively related to successive chain relays which relays will actuate upon said rotary member seizing said contacts in predetermined order for the purpose of changing the said switch to function as a selector.

37. A switch having a normal rotary movement responsive to a first series of impulses applied thereto, a first set of wipers carried by a shaft of said switch accessible to a normal level, a second set of wipers carried by said shaft accessible to a selector bank, said first wipers successively passing over said contacts in response to predetermined successive series of impulses corresponding to digits of a called number and releasing to normal position at the termination of each said series of impulses, predetermined contacts conductively related to successive chain relays which relays will actuate upon said rotary member seizing said contacts in predetermined order for the purpose of changing the said switch to function as a selector, said switch disassociating itself operatively upon succession of impulse series not being in predetermined order.

38. In a telephone system, a selector having a plurality of sets of incoming terminals, means including a switch for selecting one of the said sets of terminals, and means operative to cause different specific functioning of the selector whereby it will forthwith automatically function or only be subject to directive control depending upon which set of terminals is selected.

39. In a selector, a two-winding relay normally related to the leading-in conductors of the selector, the two windings being differentially disposed and exerting a neutral operative effort, a source of current for operating the relay, means associated with one of the said talking conductors for destroying the said neutral operative effort of the windings of the relay for causing it to operate, and means under control of the relay for initiating and sustaining the selective operation of the selector regardless of the actuated period of the relay.

40. In a selector, a two-winding relay normally related to the leading-in talking conductors of the selector, the two windings being differentially disposed and exerting a neutral operative effort, a source of current for operating the relay, means

- associated with one of the said talking conductors for destroying the said neutral operative effort of the windings of the relay for causing it to operate, and means under control of the relay for initiating and sustaining the selective operation of the selector regardless of the actuated period of the relay.
41. In a selector having a first directed primary movement directly from its normal restored position to select a group of lines and an automatically initiated secondary movement to select an idle line of the said group, the selector having an alternative second primary movement directly from its normal restored position, leading-in talking conductors for the selector, a two-winding relay normally having its windings serially connected with the leading-in talking conductors of the selector, the two windings being differentially disposed for exerting a neutral operative effort, a source of current for energizing the winding of the relay, means associated with one of said talking conductors for destroying the said neutral operative effort of the energized windings of the relay for causing it to operate, means responsive to the operation of the relay for initiating the said alternative second primary movement, means for effecting said directed primary movement without operating said relay, and automatically applied means for effecting said secondary movement consequent to effecting said directed primary movement.
42. In a selector having a directed primary movement to select a group of lines and an automatically initiated secondary movement to select an idle line of the said group, the selector having an alternative primary movement, a two-winding relay normally related to the leading-in conductors of the selector, the two windings being differentially disposed and exerting a neutral operative effort, a source of current for operating the relay, and means associated with one of the said talking conductors for destroying the said neutral operative effort of the windings of the relay for causing it to operate, means under control of the relay for initiating the said alternative primary movement, and automatic means for excluding the windings of the two-winding relay consequent to the first off-normal movement of the selector.
43. In a telephone system, a selector, leading-in conductors for the selector, a first relay, a second relay in series with the said first relay, a source of current for operatively energizing the said relays in series with the leading-in conductors, means for maintaining the selector in a normal position when first seized while said relays are operatively energized, means for attenuating the current traversing the relays below the sustaining requirement of only said second relay to cause said second relay to retract while maintaining said first relay actuated, and means under control of said second relay made operative consequent to said retraction for initiating the automatic hunting operation of the selector directly from its said normal position when seized.
44. In a telephone system, a switch mechanism, a leading-in talking conductor for the switch mechanism, a first relay, a second relay in series with said first relay, a source of current for operatively energizing the said relays in series with the leading-in talking conductor, means for maintaining the selector in a normal position when first seized while said relays are operatively energized, means for attenuating the current
- traversing the relays below the sustaining requirement of only said second relay to cause it to retract while maintaining said first relay actuated, and means under control of said second relay made operative consequent to said retraction for initiating the automatic hunting operation of the switch mechanism directly from its said normal position when seized.
45. In a telephone system, an automatic switch having a directed primary movement to select a group of lines and an automatically initiated secondary movement to select an idle line of the selected group, the switch having an alternative primary hunting movement direct from normal, leading-in talking conductors for the switch, a calling device on the leading-in line for directively operating the switch, a relay serially connected with the leading-in conductors, a source of current for energizing the relay, means associated with the leading-in conductors for attenuating the current strength energizing the relay below the value required to sustain it for causing it to retract, and means under control of said relay effective upon its retraction for initiating the said alternative movement.
46. In a telephone system, a selective switch having wiper mechanism for movement in a first plane from normal and an alternative movement from normal in a second plane, a leading-in conductor for the switch, and means directively controlled over the leading-in conductor for causing the switch to effect a movement from normal in either said first or second plane at will.
47. In a telephone system, a selective switch having a wiper mechanism for movement in a first plane from normal and an alternative movement from normal in a second plane, a leading-in conductor for the switch, a first and a second impulse sender connected to the leading-in conductor, and means responsive to operating the said first sender effective to operate the switch in the said first plane from normal, and means responsive to operating the said second sender effective to operate the switch in the said second plane from normal.
48. In a telephone system, a selective switch having wiper mechanism for movement in a first plane from normal and an alternative movement from normal in a second plane, a leading-in conductor for the switch, a first and a second impulse sender associated with the leading-in conductor, a first and a second relay of the switch operatively energized in a path including the leading-in conductor, means including the said first impulse sender for operating both said relays, means including the said second impulse sender for operating one of the relays while the other sustains, and means differently operative depending upon which impulse sender is operated for effecting one or the other said movements of the wiper mechanism.
49. In a switch having a primary movement to select a group of lines and a secondary movement to select a line of the group, the switch having an alternative primary movement from normal, a first and a second relay serially related to the leading-in talking conductors of the switch, the said second relay being marginally adjusted with respect to the said first relay, a source of current for operatively energizing the said relays, means associated with the said leading-in conductors for attenuating the strength of current energizing the said relays below the sustaining requirement of the said second relay for causing the said second relay to retract, means under control of said

- second relay for initiating the said alternative movement, and means for excluding the windings of the said second relay consequent to the first off-normal movement of the switch. 50. In a telephone system, a selective switch having wiper mechanism for directive step-by-step first movement from normal in a first plane, and an alternative second hunting movement from normal in a second plane, a leading-in conductor for the switch, a first and a second impulse sender connected to the leading-in conductor, and means responsive to operation of the said first sender for causing the wiper mechanism to effect the said first movement and operation 10 of the said second sender for causing the wiper mechanism to effect the said second movement. 51. In a telephone system, a selective switch having a wiper mechanism for a directive selection first movement directly from normal, and an alternative second hunting movement directly from normal, a leading-in conductor for the switch, a first and a second impulse sender connected to the leading-in conductor, and means responsive to operation of the said first sender for causing the switch to effect the said first movement and operation of the said second sender for causing the wiper mechanism to effect the said second movement. 52. In a switch having a primary movement to select a group of lines and a secondary movement to select a line of the group, the switch having two alternative primary movements with respect to the first said primary movement, a first and a second relay serially related to the leading-in conductors of the switch, the first said relay having two-windings differentially connected and the said second relay having its winding in series with the windings of the said first relay, the second said relay being marginally adjusted, a source of current for operatively energizing the said relays, means associated with the said leading-in conductors for attenuating the strength of current energizing said relays below the sustaining requirement of the said second relay for causing said second relay to be retracted, means associated with the said leading-in conductors for causing the current values in the windings of the said first relay to become different whereby the said first relay will operate, and means under control of the first said relay and the second said relay respectively for initiating one or the other of the said alternative primary movements. 53. In a telephone system, a trunk line in which two talking conductors thereof lead to a linking switch, a first and a second relay in the switch, the first relay having two windings connected differentially in series, the second relay having two windings connected cumulatively in series, the windings of said first relay and said second relay being in series relation with the two talking conductors and a source of current so the said first relay will not be operatively energized and the said second relay will be operatively energized, a sending device for momentarily opening the series circuit whereby said second relay will deactivate and reactivate in conformance with the said opening, means under control of said second relay for causing the operation of the said switch in a primary direction directive in accordance with the operation of the sending device, means under control of said first relay for initiating an alternative primary operation of the said switch, and means controlled over one of the said two talking conductors for causing the said first relay to operate. 54. In a telephone system, a trunk line in which two talking conductors thereof lead to a linking switch, a first and a second relay in the switch connected in series relation with the said two talking conductors, the said second relay being marginally adjusted with relation to the said first relay, a sending device for momentarily opening the said series circuit whereby said relays will be deactivated and reactuated in conformance with the said opening, means under control of said first relay for causing the operation of the said switch in a primary direction directive in accordance with the operation of the sending device, means under control of the said second relay consequent to its deactivation for initiating an alternative primary operation of the said switch if the said first relay is actuated, and means controlled over the said two conductors for causing the said second relay to deactivate while maintaining the said first relay actuated. 55. In a selector having alternative sets of incoming terminals, means including a switch for seizing either set of terminals, and means operative to cause alternate specific functioning of the selector whereby it will forthwith automatically function or only be subject to directive control depending upon which set of terminals is seized. 56. In a telephone system, a selector switch which will test for an idle trunk of a selected group, trunks extending from the bank contacts thereof, and means for operating said switch as a selector of one numerical order to select certain said trunks and also as a selector of a higher numerical order to select others of said trunks. 57. In a telephone system a selector with a trunk leading from an accessible contact set in a bank level to a selector of a first numerical order, a second trunk leading from an accessible contact set in a bank level to a selector of a higher numerical order than the second said selector, means controllable from a contact made by the first said selector rotating at a predetermined level to determine which said trunk may be seizable. 58. In a telephone system, a selector controlled over a two-conductor leading-in trunk and having access to either of two groups of trunks through corresponding wiper sets alternatively, and means at the end of the trunk remote from the switch controlled automatically incidental to the seizure of the said end of the trunk by a preceding switch for determining which set of wipers and cooperative trunks shall be accessible. 59. In a telephone system, a selector controlled over the two talking conductors of a leading-in trunk and having access to one of two groups of trunks through corresponding wiper sets alternatively, and means at the end of the trunk remote from the switch controlled automatically incidental to the seizure of the said end of the trunk by a preceding switch for determining which set of wipers and cooperative trunks shall be accessible. 60. In a telephone system, a switch controlled over the two talking conductors of a leading-in trunk and having access to one of two groups of lines through corresponding wiper sets alternatively, and means at the end of the trunk remote from the switch controlled automatically incidental to the seizure of the said end of the trunk by a preceding switch for determining which set of wipers and cooperative lines shall be accessible.

61. In a telephone system, a switch controlled over the two talking conductors of a leading-in trunk and having access to any of a plurality of groups of lines through corresponding wiper sets, and means at the end of the trunk remote from the switch controlled automatically incidental to the seizure of the said end of the trunk by a preceding switch for determining which set of wipers and cooperative lines shall be accessible. 80
- 10 62. In a telephone system, a switch arranged to perform the functions of a linking switch, a plurality of sets of wipers for said switch, series of contact sets for each set of wipers, means for moving said wipers to simultaneously traverse said contacts, a connecting circuit extending to said switch consisting only of two talking conductors, multiple terminal contacts for said switch at which said circuit may be selected, and means dependent upon which of said multiple terminal contacts said circuit is selected for determining which of said wiper sets will be rendered operative. 85
- 15 63. In a telephone system, a telephone line and impulse device, an automatic switch connected to said line, a shaft and wipers for said switch having vertical and rotary movement, means responsive to the directive operation of the impulse device for correspondingly operating the shaft and wipers rotarily from normal, means for 90 restoring the shaft and wipers, and means responsive to said restoration whereby subsequent directive impulses from the impulse device will cause the shaft and wipers to correspondingly operate vertically from normal. 95
- 20 64. In a telephone system, a telephone line and impulse device, an automatic switch connected to said line, a shaft and wipers for said switch having vertical and rotary movement, means responsive to the directive operation of the impulse device for correspondingly operating the shaft and wipers rotarily from normal, means for restoring the shaft and wipers, and means responsive to said restoration whereby subsequent directive impulses from the impulse device will cause the 100 shaft and wipers to correspondingly operate vertically from normal, and automatic means effective upon the termination of the vertical movement for rotating the shaft at its attained vertical position. 105
- 25 65. In a telephone system, a telephone line and impulse device, a trunk line extending in a branch from said telephone line and a selective switch terminating said branch, a shaft switch terminating said line, means for operating the 110 shaft of the shaft switch primarily to rotate the shaft directly from normal responsive to a directive operation of the impulse device, means responsive to a predetermined rotary movement of the switch shaft to restore the shaft, means 115
- 30 responsive to the restoration of the shaft whereby subsequent directive impulses from the impulse device will cause the shaft to correspondingly operate vertically directly from normal, means effective upon the attainment of the selected vertical position for automatically rotating the shaft in hunting operation, means whereby the said selective switch will operate responsive to the impulse device coincidently with the said rotary movement of the shaft switch, and means for 120 disconnecting the branch from the said selective switch and restoring the said selective switch responsive to the said predetermined rotary movement of the said switch shaft. 125
- 35 66. In a telephone system, a calling line and impulse device, a dual functioning switch on the calling line, the said switch having a normal and off-normal levels, a selective switch on a branch of the calling line, a first trunk line and a second trunk line, a linking switch on said first trunk line, a called line accessible from the first said switch, means controlled by the impulse device for directly operating said dual functioning switch over its normal level, means for directly operating said selective switch coincidently with the said directed operation of said dual functioning switch to extend a connection from the calling line to said first trunk line, means for restoring said dual functioning switch and for disconnecting the said branch responsive to the said operation of said dual functioning switch if the said operation is a predetermined one, and means responsive to a subsequent directive operation of the impulse device for operating the said dual functioning switch vertically to a level and then as a hunting switch to extend the calling line toward the called line. 130
- 40 67. In a telephone system, a calling line, a calling device on the calling line, a dual functioning switch on the calling line, a called line, another line, connective switches, a said connective switch connected on a branch of the calling line, means for successively operating and thereupon restoring the dual functioning switch directly responsive to the calling device, means for directly extending the calling line from the said 135 connective switch through other said connective switches responsive to sending successive numerical order digit series from the calling device corresponding to the number of the called line coincidently with the directive operation of the dual functioning switch, the said digits numerically corresponding in order to the digits of said other line, the said other line being in the direction of the said progressed extension, means for disconnecting the said branch responsive to sending a predetermined digit series of a predetermined numerical order of the called line number, the said predetermined digit series and numerical order not being pertinent to the said other line, and means for then directly operating the dual 140 functioning switch by the calling device directly from normal as a connective switch of the next higher numerical order with respect to the last digit series sent, to extend the calling line towards the called line. 145
- 45 68. In an automatic two dimension wiper switch, means responsive to directive calling device control for primarily rotating its wipers directly from normal over a normal level, means for thereupon automatically restoring the wipers to normal, and means thereby effective to vary the switch for then operating the switch under said directive control directly from normal to step its wipers vertically. 150
- 50 69. In an automatic two-dimension wiper switch, means responsive to directive calling device control for primarily moving its wipers in a predetermined plane, means for thereupon automatically restoring the wipers to normal, and means thereby effective to vary the switch for then operating the switch under said directive control to move its wipers in the other plane directly from normal. 155
- 55 70. In an automatic two-dimension wiper switch, means responsive to directive calling device control for primarily rotating its wipers directly from normal over a normal level in one dimension, means for thereupon automatically restoring the wipers to normal, means thereby effective to vary the switch for then operating the 160

- switch under said directive control directly from normal to step its wipers vertically in the other dimension, and means made operative consequent to the last said operation to enable the wipers to 5 be again operated in the first said dimension without first restoring to normal.
71. In an automatic two-dimension wiper switch, means responsive to directive calling device control for primarily rotating its wipers 10 directly from normal over a normal level in one dimension, means for thereupon automatically restoring the wipers to normal, means thereby effective to vary the switch for then operating the switch under said directive control directly from 15 normal to step the wipers vertically in the other dimension, and means made operative consequent to the last said operation to cause the wipers to hunt in the first said dimension without first restoring to normal.
72. In an automatic two-dimension wiper switch, means responsive to directive calling device control for primarily moving its wipers in a predetermined plane, means for thereupon automatically restoring the wipers to normal, means 20 thereby effective to vary the switch for then operating the switch under said directive control to move its wipers in the other plane directly from normal, and means made operative consequent to the last said operation to enable the 25 wipers to be again operated in the first said plane without first restoring to normal.
73. In an automatic two-dimension wiper switch, means responsive to directive calling device control for primarily moving its wipers 30 in a predetermined plane, means for thereupon automatically restoring the wipers to normal, means thereby effective to vary the switch for then operating the switch under said directive control to move its wipers in the other plane directly from normal, and means made operative consequent to the last said operation to cause the 35 wipers to hunt in the first said plane without first restoring to normal.
74. In a telephone system, a calling line and 40 impulse device, a dual functioning switch on the calling line, the said switch having a normal and off-normal levels, a selective switch on a branch of the calling line, a first trunk line and a linking switch on said first trunk line, a called line accessible from the first said switch, means 45 controlled by the impulse device for directly operating said dual functioning switch over its normal level, means for directly operating said selective switch coincidently with the said directed operation of said dual-functioning switch to extend a connection from the calling line to 50 said first trunk line, means for restoring said dual-functioning switch and for disconnecting the said branch responsive to the said operation of said dual functioning switch if the said operation is a predetermined one, and means responsive to subsequent directive operation of the 55 impulse device for operating the said dual functioning switch vertically to a level and then on the level to extend the calling line toward the 60 called line.
75. In a telephone system, a branched two-conductor talking and operating trunk line and connected automatic switch having a normal 65 resting position, switch mechanism for seizing the trunk over any of its said branches, control mechanism interposed in the trunk intermediate of the branches and the automatic switch, the 70 switch having alternative characters of selective 75 operations directly from its normal resting po-
- sition, each said branch corresponding to a specific one of said operations of the switch, and means including the said interposed mechanism depending upon what branch the trunk is seized over for automatically causing the switch to operate directly selectively from its normal resting position in correspondence with the branch seized.
76. In a telephone system, a calling line, a directive device on the calling line, the calling line terminating in a selective switch having two wiper sets, a set of trunks accessible to each said set of wipers, the sets of trunks belonging to two different numerical orders, one set of wipers having normal operative access to its cooperative set of trunks and the other set of wipers having alternative operative access to its cooperative set of trunks, a calling line reached over each set of trunks respectively, means responsive to the directive device for causing the switch to operate from normal in accordance with a first digit of one of the called lines to set the switch with relation to the set of trunks of one numerical order to extend the calling line through the normal wipers to a trunk toward one called line, means responsive to the directive device for causing the 100 switch to operate from normal in accordance with a first digit of another one of the called lines to correspondingly operate the switch and restore it without effecting a connection to a trunk, means responsive incidental to the said restoration of the 105 switch to switch the switch circuits to the alternative set of wipers from the normal set of wipers, means responsive to a second numerical order digit of the said another called line for operating the switch directly from normal to extend 110 the calling line through the alternative set of wipers to a trunk line toward the said another called line, and means whereby the same number of numerical order digits will be sent to complete the connection from the calling line to either 115 120 called line, but wherein wipers of the switch will not be set upon a trunk until one or two digits have been sent depending upon what line is being called.
77. In a telephone system, a calling line leading to a first switch having sets of fixed terminals thereon of a plurality of groups of trunks, a set of wipers of said switch having a normal resting position for extending the calling line to a selected said set of fixed terminals, each said 125 group leading to a corresponding group of switches for further extending a call from the said first switch in the direction of a corresponding plurality of called lines, each called line reached by sending a plurality of numerical order digits of which the first digit is the same respectively, a calling device for sending the 130 digits effective to operate the switches, means dependent upon sending a plurality of successive numerical order digits to extend the calling line 135 towards the called line for determining which said group on said first switch will contain the trunk over which the connection from the calling line to the called line will be extended, and means whereby then operating the sending device in accordance with a predetermined next following numerical order digit of the called line will correspondingly operate the set of wipers of said first switch from their normal resting position to 140 operatively connect the calling line to a trunk of the determined group in extending the connection towards the called line.
78. In a telephone system, a calling line leading to a first switch having sets of terminals thereon of a plurality of groups of trunks, each said 145 150

- group leading to a corresponding group of switches for further extending a call from the said first switch in the direction of a corresponding plurality of called lines, each called line reached by sending a plurality of numerical order digits of which the first digit is the same respectively, a calling device for sending the digits effective to the switches, a mechanism for determining which said group of trunks the connection will be extended over from the said first switch in extending the call from the said first switch towards the line called, and means operated responsive to the first and second numerical order digits sent from the calling device effective to the said first switch and a switch of second said switches respectively for operating the said mechanism.
79. In a telephone system, a calling line and connected switch, a first, second and third group of trunks and connected corresponding switches leading from the first switch, a fourth group of trunks and connected corresponding switches, called lines corresponding to the second, third and fourth groups respectively, release mechanism for the first said switch, a manually operated directive device on the calling line, means responsive to a first operation of the directive device for operating the first said switch to seize a trunk of the first group, means responsive to a second operation of the directive device for operating the switch of the seized trunk of the first group, means responsive to the said directed operation of the last operated switch dependent upon what the second or last said directed operation of the directive device is for either extending the call to the fourth group of trunks toward the first called line or for restoring the first switch, and means responsive to a third directed operation of the directive device for re-operating the said first switch if released to select over the second or third trunk group to extend the connection toward the second or third called line depending upon what directed movement was effected by the switch of the seized trunk of the first group responsive to the second directed operation of the directive device.
80. In a telephone system, an automatic wiper switch, automatic means for causing the switch to itself automatically maintain the movement of the wipers, and automatic means for at will alternatively causing the switch to move its wipers step-by-step directively.
81. In a telephone system, a calling line and connected first switch, a manually controlled directive mechanism on the calling line, a branched two-conductor talking and operating trunk and connected second hunting switch, groups of lines leading from the second switch, each said branch corresponding to a said line group, means responsive to a single directed operation of the directive device for correspondingly operating the first switch to seize any said branch at will and for causing the second switch to hunt with specific relation to the line group corresponding to the branch seized and seize the first idle line of the group to complete a connection from the calling line.
82. In a telephone system, a calling line and connected first switch, a manually controlled directive mechanism on the calling line, a branched talking and operating trunk and connected second hunting switch, groups of lines leading from the second switch, each said branch corresponding to a said line group, means responsive to a single directed operation of the direc-

- tive device for correspondingly operating the first switch to seize any said branch at will and for causing the second switch to hunt with specific relation to the line group corresponding to the branch seized and seize the first idle line of the group to complete a connection from the calling line.
83. In a telephone system, a calling line and connected first switch, a manually controlled directive device on the calling line, a branched two-conductor talking and operating trunk and connected second hunting switch, called lines leading from the second switch, each said branch corresponding to a said called line, means responsive to a single directed operation of the directive device for correspondingly operating the first switch to seize any said branch at will and for causing the second switch to seize the line corresponding to the branch seized to complete a connection from the calling line.
84. In a telephone system, a calling line and connected first switch, a manually controlled directive device on the calling line, a branched trunk and connected second hunting switch, called lines leading from the second switch, each said branch corresponding to a said called line, means responsive to a single directed operation of the directive device for correspondingly operating the first switch to seize any said branch at will and for causing the second switch to seize the line corresponding to the branch seized to complete a connection from the calling line.
85. In a telephone system, a branched two-conductor talking and operating trunk and connected switch, a plurality of trunk groups leading from the switch, switch means for seizing the trunk over any of its branches, means for causing the switch to hunt consequent to the line being seized over one of its branches, and means dependent upon which branch the line is seized over which will determine which trunk group the hunting will be with relation to.
86. In a telephone system, a branched trunk and connected switch, a plurality of trunk groups leading from the switch, switch means for seizing the trunk over any of its branches, means for causing the switch to hunt consequent to the line being seized over one of its branches, and means dependent upon which branch the line is seized over which will determine which trunk group the hunting will be with relation to.
87. In a telephone system, a branched two-conductor talking and operating trunk and connected switch, two groups of trunks leading from the switch, means for seizing the trunk over either of two branches, and means made operative consequent to the seizure for causing the switch to hunt with predetermined relation to one or the other group depending upon the branch seized.
88. In a telephone system, a branched trunk and connected switch, two groups of trunks leading from the switch, means for seizing the trunk over either of two branches, and means made operative consequent to the seizure for causing the switch to hunt with predetermined relation to one or the other group depending upon the branch seized.
89. In a telephone system, a branched two-conductor talking and operating trunk and connected switch, a plurality of groups of lines leading from the switch, a plurality of sets of alternatively operative wipers, each wiper set specific to a line group, each said branch specific to a said wiper set and a said group respectively,

switch means for seizing the trunk over any said branch at will, and means made operative consequent to the seizure of a said branch for causing its corresponding wiper set to hunt with relation to its corresponding line group to seize an idle line and effect a talking connection thereover.

90. In a telephone system, a branched trunk and connected switch, a plurality of groups of lines leading from the switch, a plurality of sets of alternatively operative wipers, each wiper set specific to a line group, each said branch specific to a said wiper set and a said group respectively, switch means for seizing the trunk over any said branch at will, and means made operative consequent to the seizure of a said branch for causing its corresponding wiper set to hunt with relation to its corresponding line group to seize an idle line and effect a talking connection thereover.

91. In a telephone system, a branched two-conductor talking and operating trunk and connected switch, a plurality of trunk groups corresponding to the branches leading from the switch, switch means for seizing the trunk over any of its branches, means for causing the switch to hunt consequent to the trunk being seized over one of its branches, means dependent upon which branch the trunk is seized over which will determine if a corresponding said trunk group will be hunted over or if the switch will remain in the position as when seized, a manual directive control mechanism, and means responsive to the said control mechanism applied at will over the seized branch, if the switch remains in the position as when seized, for operating the switch with selective relation to a said trunk group.

92. In a telephone system, a branched trunk and connected switch, a plurality of trunk groups corresponding to the branches leading from the switch, switch means for seizing the trunk over any of its branches, means for causing the switch to hunt consequent to the trunk being seized over one of its branches, means dependent upon which branch the trunk is seized over which will determine if a corresponding said trunk group will be hunted over or if the switch will remain in the position as when seized, a manual directive control mechanism, and means responsive to the said control mechanism applied at will over the seized branch, if the switch remains in the position as when seized, for operating the switch with selective relation to a said trunk group.

93. In a telephone system, a branched two-conductor talking and operating trunk and connected switch, said switch operating alternatively as a hunting switch and as a step-by-step directed switch, two groups of trunks leading from the switch, switch means for seizing the line over any of its branches, a manually operated control device, means operated dependent upon what branch is seized for causing the switch to thereupon hunt over a predetermined one of said groups, and means operative dependent upon what branch is seized for rendering the switch thereupon under directive control of the control device for being step-by-step operated into selective relation to the other said group.

94. In a telephone system, a branched trunk and connected switch, said switch operating alternatively as a hunting switch and as a step-by-step directed switch, two groups of trunks leading from the switch, switch means for seizing the line over any of its branches, a manually operated control device, means operated dependent

upon what branch is seized for causing the switch to thereupon hunt over a predetermined one of said groups, and means operative dependent upon what branch is seized for rendering the switch thereupon under directive control of the control device for being step-by-step operated into selective relation to the other said group.

95. In a telephone system, a branched two-conductor talking and operating trunk and connected switch, said switch operating alternatively as a hunting switch and as a step-by-step directed switch, switch means for seizing the trunk over any of its branches, a manually operated control device, means operative dependent upon what branch is seized for causing the switch to thereupon hunt or remain as when seized, and means controlled over the trunk responsive to the control device if the switch remains as when seized for at will operating the switch.

96. In a telephone system, a branched trunk and connected switch, said switch operating alternatively as a hunting switch and as a step-by-step directed switch, switch means for seizing the trunk over any of its branches, a manually operated control device, means operative dependent upon what branch is seized for causing the switch to thereupon hunt or remain as when seized, and means controlled over the trunk responsive to the control device if the switch remains as when seized for at will operating the switch.

97. In a telephone system, a two-conductor talking and operating trunk having a plurality of branches at its near end, an automatic switch connected to the far end of the trunk, a plurality of groups of trunks leading from the switch, a common wiper set of the switch normally subject to connecting in any said group, a relay operative to determine to which group the wipers will thereupon be subject to connection in and which will incidentally determine that other said groups will be thereupon barred from connection in by the wipers, a ground path for inclusion with the energizing circuit of the relay effective to operate the relay, switch means for seizing the trunk over any one of said branches, and means automatically effective depending upon which branch the trunk is seized over for including the ground to operate the relay.

98. In a telephone system, a trunk having a plurality of branches at its near end, an automatic switch connected to the far end of the trunk, a plurality of groups of trunks leading from the switch, a common wiper set of the switch normally subject to connecting in any said group, a relay operative to determine to which group the wipers will thereupon be subject to connection in and which will incidentally determine that other said groups will be thereupon barred from connection in by the wipers, a ground path for inclusion with the energizing circuit of the relay effective to operate the relay, switch means for seizing the trunk over any one of said branches, and means automatically effective dependent upon which branch the trunk is seized over for including the ground to operate the relay.

99. In a telephone system, a two-conductor talking and operating trunk having two branches at its near end, an automatic switch connected to the far end of the trunk, two groups of trunks leading from the switch, a common wiper set of the switch normally subject to connecting in either said group, switch means for alternatively seizing the trunk over one or the other said

- branch, and means effective depending upon which branch the trunk is seized over for barring one or the other said group against connection by the wiper set.
- 5 100. In a telephone system, a trunk having two branches at its near end, an automatic switch connected to the far end of the trunk, two groups connected in either said group, switch means for alternatively seizing the trunk over one or the other said branch, and means effective depending upon which branch the trunk is seized over for barring one or the other said group against connection by the wiper set. 80
- 10 101. In a telephone system, a two-conductor talking and operating trunk having a plurality of branches at its near end, an automatic switch connected to the far end of the trunk, a plurality of groups of trunks leading from the switch, a common wiper set of the switch normally subject to connecting to any said group, switch means for seizing the trunk over any one of said branches, and means effective depending upon which branch the trunk is seized over for determining to which group the wipers will thereupon be subject to connection in and incidentally barring others of said groups from connection. 85
- 15 102. In a telephone system, a trunk having a plurality of branches at its near end, an automatic switch connected to the far end of the trunk, a plurality of groups of trunks leading from the switch, a common wiper set of the switch normally subject to connecting to any said group, switch means for seizing the trunk over any one of said branches, and means effective depending upon which branch the trunk is seized over for determining to which group the wipers will thereupon be subject to connection in and incidentally barring others of said groups from connection. 90
- 20 103. In a telephone system, a two-conductor talking and operating trunk having a plurality of branches at its near end, an automatic switch connected to the far end of the trunk, a plurality of groups of trunks leading from the switch, a common wiper set of the switch normally subject to connecting to any said group, a relay operative for determining to which group the wipers will thereupon be subject to connection in and incidentally barring others of said groups, a resistance for inclusion with the energizing circuit of the relay effective to operate the relay, switch means for seizing the trunk over any one of said branches, and means automatically effective depending upon which branch the trunk is seized over for including the resistance to operate the relay. 95
- 25 104. In a telephone system, a trunk having a plurality of branches at its near end, an automatic switch connected to the far end of the trunk, a plurality of groups of trunks leading from the switch, a common wiper set of the switch normally subject to connecting to any said group, a relay operative for determining to which group the wipers will thereupon be subject to connection in and incidentally barring others of said groups, a resistance for inclusion with the energizing circuit of the relay effective to operate the relay, switch means for seizing the trunk over any one of said branches, and means automatically effective depending upon which branch the trunk is seized over for including the resistance to operate the relay. 100
- 30 105. In an automatic telephone system, a two-dimension wiper switch having a normal restored position for its wipers, levels of bank contacts of the switch, a two-conductor talking and operating leading-in line for the switch, manually operated directive mechanism connected on the leading-in line, means responsive to the directive mechanism to move the wipers from their normal restored position in one dimension to sweep a said level of bank contacts, means for alternatively operating said wipers from their normal restored position by the directive mechanism on the other dimension and then sweep another level of said bank contacts in the said one dimension. 105
- 35 106. In an automatic telephone system, a two-dimension wiper switch having a normal restored position for its wipers, levels of bank contacts of the switch, a leading-in line for the switch, manually operated directive mechanism connected on the leading-in line, means responsive to the directive mechanism to move the wipers from their normal restored position in one dimension to sweep a said level of bank contacts, and means for alternatively operating said wipers from their normal restored position by the directive mechanism on the other dimension and then sweep another level of said bank contacts in the said one dimension. 110
- 40 107. In a telephone system, a two-conductor talking and operating line, an automatic dual-functioning switch connected at the far end of the line, the switch operating as a step-by-step directly controlled switch directly from normal or as an automatically functioning selective switch directly from normal, a relay, and means including the relay controlled over the line from the near end of the line for determining which operation the switch will perform. 115
- 45 108. In a telephone system, a line, an automatic dual-functioning switch connected at the far end of the line, the switch operating as a step-by-step directly controlled switch directly from normal or as an automatically functioning selective switch directly from normal, a relay, and means including the relay controlled over the line from the near end of the line for determining which operation the switch will perform. 120
- 50 109. In a telephone system, a switch arranged to perform the functions of any one of a plurality of different kinds of automatic telephone switches, a wiper for the switch, a two-conductor talking and operating trunk leading into said switch, a relay operated over the trunk, means for operating the relay without beforehand moving said wiper, and means controlled by said relay when so operated for determining which of said functions said switch will perform. 125
- 55 110. In a telephone system, a switch arranged to perform the functions of any one of a plurality of different kinds of automatic telephone switches, a wiper for the switch, a trunk leading into said switch, a relay operated over the trunk, means for operating the relay without beforehand moving said wiper, and means controlled by said relay when so operated for determining which of said functions said switch will perform. 130
- 60 111. In a telephone system, a two-conductor talking and operating trunk, an automatic dual-functioning switch connected to the far end of the trunk which will operate either as a numerical switch or as a non-numerical switch, a wiper for the switch, a relay connected to the trunk, and controlled from the near end of the trunk, means for operating the relay without beforehand moving said wiper, and means including the 135
- 65 112. In a telephone system, a two-conductor talking and operating trunk, an automatic dual-functioning switch connected to the far end of the trunk which will operate either as a numerical switch or as a non-numerical switch, a wiper for the switch, a relay connected to the trunk, and controlled from the near end of the trunk, means for operating the relay without beforehand moving said wiper, and means including the 140
- 70 113. In a telephone system, a two-conductor talking and operating trunk, an automatic dual-functioning switch connected to the far end of the trunk which will operate either as a numerical switch or as a non-numerical switch, a wiper for the switch, a relay connected to the trunk, and controlled from the near end of the trunk, means for operating the relay without beforehand moving said wiper, and means including the 145
- 75 114. In a telephone system, a two-conductor talking and operating trunk, an automatic dual-functioning switch connected to the far end of the trunk which will operate either as a numerical switch or as a non-numerical switch, a wiper for the switch, a relay connected to the trunk, and controlled from the near end of the trunk, means for operating the relay without beforehand moving said wiper, and means including the 150

- relay for determining which said function the switch shall perform.
112. In a telephone system, a trunk, an automatic dual-functioning switch connected to the far end of the trunk which will operate either as a numerical switch or as a non-numerical switch, a wiper for the switch, a relay connected to the trunk and controlled from the near end of the trunk, means for operating the relay without beforehand moving said wiper and means including the relay for determining which said function the switch shall perform.
113. In a telephone system, an automatic switch having two sets of simultaneously movable wipers and corresponding groups of line bank terminals, corresponding bank terminals of the two groups being coincidently engaged by both sets of wipers, said wiper sets being alternatively operative, a two-conductor talking and operating line leading-in to the switch, a calling station for connection to the line, a relay for alternating the operativeness of the wiper sets, said relay being operatively effective responsive to a temporary abnormal current condition occurring on the line, and a contact device controlled from the calling station for at will effecting the said abnormal condition on the line.
114. In a telephone system, an automatic switch having two sets of simultaneously movable wipers and corresponding groups of line bank terminals, corresponding bank terminals of the two groups being coincidently engaged by both sets of wipers, said wiper sets being alternatively operative, a talking and operating line leading-in to the switch, a relay for alternating the operativeness of the wiper sets, said relay being operatively effective responsive to a temporary abnormal condition occurring on the line, and a contact device for at will effecting the said abnormal condition on the line, and for effacing the said abnormal condition without destroying the operativeness of the condition effected.
115. In a telephone system, a branched two-conductor talking and operating trunk, switch mechanism connected to a non-branched end of the trunk and having wiper sets and corresponding bank contact groups, the said wiper sets coincidently sweeping their respective companion sets of bank contact groups, each said branch corresponding to a specific said wiper set and its companion bank contact group, switch means for seizing any one of said branches, and means for rendering only the said wiper set corresponding to the branch seized in operative relation with respect to the trunk and its companion bank contact group.
116. In a telephone system, a branched two-conductor talking and operating trunk and connected switch, a plurality of groups of trunks leading from the switch, each said branch corresponding to a specific trunk group, a relay terminating each trunk, a secondary circuit specific to and controlled by each relay, switch means for seizing any one of said branches, manually controlled directive mechanism, means operative consequent to a branch being seized for causing the branched trunk to be extended to a line of its corresponding trunk group, and means including the directive mechanism and the seized branch for directly operating the relay of the connected trunk.
117. In a telephone system, a branched trunk and connected switch, a plurality of groups of trunks leading from the switch, each said branch corresponding to a specific trunk group, a relay terminating each trunk, a secondary circuit specific to and controlled by each relay, switch means for seizing any one of said branches, manually controlled directive mechanism, means operative consequent to a branch being seized for causing the branched trunk to be extended to a line of its corresponding trunk group, and means including the directive mechanism and the seized branch for directly operating the relay of the connected trunk.
118. In a telephone system, a branched two-conductor talking and operating trunk and connected wiper switch, a plurality of groups of trunks leading from the switch, a wiper set for the switch specific to each trunk group, each said branch corresponding to a said wiper set and its trunk group, a relay terminating each trunk, a secondary circuit specific to and controlled by each relay, switch means for seizing any one of said branches, manually controlled directive mechanism, means operative consequent to a branch being seized for causing the branched trunk to be extended over the corresponding wiper set to a line of its corresponding trunk group, and means including the directive mechanism and the seized branch for directly operating the relay of the connected trunk.
119. In a telephone system, a branched trunk and connected wiper switch, a plurality of groups of trunks leading from the switch, a wiper set for the switch specific to each trunk group, each said branch corresponding to a said wiper set and its trunk group, a relay terminating each trunk, a secondary circuit specific to and controlled by each relay, switch means for seizing any one of said branches, manually controlled directive mechanism, means operative consequent to a branch being seized for causing the branched trunk to be extended over the corresponding wiper set to a line of its corresponding trunk group, and means including the directive mechanism and the seized branch for directly operating the relay of the connected trunk.
120. In an automatic telephone system, a single dimension wiper switch, two groups of trunks leading from said switch, a two-conductor talking and operating leading-in line for the switch, a first and a second relay, means responsive to the operation of the first relay to cause the switch to hunt with respect to one said group and responsive to the operation of the other said relay to cause the switch to hunt with respect to the other said group, and a control mechanism on the leading-in line for operating one or the other said relays at will.
121. In an automatic telephone system, a single dimension wiper switch, two groups of trunks leading from said switch, a leading-in line for the switch, a first and a second relay, means responsive to the operation of the first relay to cause the switch to hunt with respect to one said group and responsive to the operation of the other said relay to cause the switch to hunt with respect to the other said group, and a control mechanism on the leading-in line for operating one or the other said relays at will.
122. In an automatic telephone system, a two-dimension wiper switch having a normal restored position for its wipers, a two-conductor talking and operating leading-in line for the switch, manually operated directive mechanism connected on the leading-in line, means responsive to the directive mechanism to at will move the wipers in one dimension directly from normal,

- and alternative means responsive to the directive mechanism to at will move the wipers in the other dimension directly from normal.
123. In an automatic telephone system, a two-dimension wiper switch having a normal restored position for its wipers, a leading-in line for the switch, manually operated directive mechanism connected on the leading-in line, means responsive to the directive mechanism to at will move the wipers in one dimension directly from normal, and alternative means responsive to the directive mechanism to at will move the wipers in the other dimension directly from normal. 80
124. In a telephone system, a calling line, a calling impulse device on the calling line, trunk sections, switches for linking the sections, and means for directly operating certain of said switches by applying impulses thereto over trunk sections, responsive to the calling device for linking a plurality of trunk sections in tandem corresponding in number to the number of impulse series sent from the calling device or for directly operating said switches responsive to the calling device for linking a greater number of trunk sections in tandem than the number of impulse series sent by the calling device. 85
125. In a telephone system, a calling line, a calling impulse device on the calling line, trunk sections, switches for linking the sections, and means for directly operating certain of said switches responsive to the calling device for linking a plurality of trunk sections in tandem corresponding in number to the number of impulse series sent from the calling device or for directly operating said switches by applying impulses thereto over trunk sections responsive to the calling device for linking a greater number of trunk sections in tandem than the number of impulse series sent by the calling device wherein in the section immediately antecedent to the terminating section linked by last said operation of the switches is common to said connections. 90
126. In a telephone system, a calling line, a plurality of connective switches, an impulse calling device on the calling line for sending a train of series of one or more impulses, means responsive to the impulses from the impulse device for directly operating certain of said switches corresponding in number to the number of series to progressively extend a connection from the calling line, and automatically applied impulse sending means responsive to specific alternative operation of the impulse device for causing a directive operation of a greater number of said switches than there are series in the train sent from the impulse device. 95
127. In a telephone system, a calling line, a plurality of connective switches, an impulse calling device on the calling line for sending a train of series of one or more impulses, means responsive to the impulses from the impulse device for directly operating certain of said switches corresponding in number to the number of series to progressively extend a connection from the calling line, and automatically applied impulse sending means responsive to specific alternative operation of the impulse device for causing a directive operation of a greater number of said switches than there are series in the train sent from the impulse device wherein the switch immediately antecedent to the last switch operated is common to said connections. 100
128. In a telephone system, a trunk line, a plurality of relays associated with said trunk line, a plurality of other trunk lines accessible to said first trunk line, means whereby the operation of each one of said relays connects said first trunk line with one of said other trunk lines, and an automatic progressively movable switch for seizing said first trunk line, and for selecting which one of said relays shall be operated and for operating the elected relay. 105
129. In a telephone system, a trunk line, other trunk lines normally disconnected therefrom, a plurality of relays associated with said first trunk line, each of said relays responsive to an impulse of different character to connect said first trunk line with any one of said other trunk lines, an automatic progressively movable switch for seizing said first trunk line, and for electing which one of said relays shall be operated and for operating the elected relay. 110
130. In a telephone system, a trunk line, a plurality of other trunk lines, a plurality of relays associated with said first trunk line, each of said relays adapted to connect said first trunk line with a different one of said other trunk lines, and an automatic progressively movable switch controlled by a calling subscriber for seizing said first trunk line and for operating any one of said relays to connect at will with any one of said other trunk lines. 115
131. In a telephone system, a trunk line, a plurality of other lines, a switch for each one of said other lines, a plurality of terminals for said trunk line, means associated with said terminals whereby when one terminal is seized, one of said switches is operated to extend the trunk to one particular one of said other lines, and whereby when a different terminal is seized, another and different one of said switches is operated to extend the trunk to its corresponding line. 120
132. In a telephone system, a trunk line, a repeater on one end of said trunk line, a plurality of relays at the other end of said trunk line, means for connecting with said repeater over a plurality of different paths, and means for operating any one of said relays responsive to the establishment of said connection, the relay operated depending upon which of said paths is used. 125
133. In a telephone system, an automatic switch having two sets of wipers, means for connecting with said switch over two different paths, means for directly operating said switch after the same is connected with, wiper switching means in said switch, and circuit arrangements such that the operation of said switching means is determined either by the route over which the switch is connected with or by the extent of its operation after it is connected with. 130
134. In a telephone system, an automatic switch having two sets of wipers, means for connecting with said switch over two different paths, means for directly operating said switch after the same is connected with, wiper switching means in said switch responsive when the switch is connected with provided the connection is established over only a particular path, and means causing said switching means to respond to a directive movement of predetermined extent in case the connection is established over only the other path. 135
135. In a telephone system, a calling line, a calling impulse device on the calling line, trunk sections, switches for linking the sections, means for directly operating certain of said switches by applying impulses thereto over trunk sections responsive to the calling device for linking a plurality of trunk sections in tandem corresponding in number to the number of impulse series sent

- from the calling device, the last switch linked into the train having a set of wipers and operating shaft therefor common to all connections made by the switch, and means for directly operating all of said switches by applying impulses thereto over trunk sections responsive to the calling device for linking a greater number of trunk sections in tandem than the number of impulse series sent by the calling device. 136. In a telephone system, a calling line, a calling impulse device on the calling line, trunk sections, switches for linking the sections, means for directly operating certain of said switches by applying impulses thereto over trunk sections responsive to the calling device for linking a plurality of trunk sections in tandem corresponding in number to the number of impulse series sent from the calling device, the last switch linked into the train having a set of wipers and operating shaft therefor common to all connections made by the switch, and means for directly operating all of said switches by applying impulses thereto over trunk sections responsive to the calling device for linking a greater number of trunk sections in tandem than the number of impulse series sent by the calling device wherein the section immediately antecedent to the terminating section linked by last said operation of the switches is common to said connections. 137. In a telephone system, a calling line, a plurality of connective switches, an impulse calling device on the calling line for sending a train of series of one or more impulses, means responsive to the impulses from the impulse device for directly operating certain of said switches into a train corresponding in number to the number of series to progressively extend a connection from the calling line, the last switch linked into the train having a set of wipers and operating shaft therefor common to all connections made by the switch, and automatically applied impulse sending means responsive to specific alternative operation of the impulse device for causing a directive operation of a greater number of said switches into the train including all first said operated switches than there are series in the train sent from the impulse device to extend a connection from the calling line. 138. In a telephone system, a calling line, a plurality of connective switches, an impulse calling device on the calling line for sending a train of series of one or more impulses, means responsive to the impulses from the impulse device for directly operating certain of said switches into a train corresponding in number to the number of series to progressively extend a connection from the calling line, the last switch linked into the train having a set of wipers and operating shaft therefor common to all connections made by the switch, and automatically applied impulse sending means responsive to specific alternative operation of the impulse device for causing a directive operation of a greater number of said switches into the train including all first said operated switches than there are series in the train sent from the impulse device to extend a connection from the calling line, and means whereby the switch immediately antecedent to the last switch operated is common to said connections. 139. In a telephone exchange system, an exchange, a subscriber's line terminating therein, a plurality of line relays for said line, manual and automatic connective link circuits at said exchange for sending a call from said line, means including a resistance normally shunted by subscriber controlled means for selectively controlling the operation of said line relays over said line conductors in series to selectively extend the calling line to said manual or automatic connective terminals. 140. In a telephone system, a central office, a subscriber's line terminating thereat, subscriber controlled means including a non-locking normally closed key, shunted by a resistance, in serial relation with said line, manual and automatic connecting link circuits at said central office for extending said line, and means at the central office controlled by said key for selectively extending the calling line to said manual or said automatic link circuit. 141. In a telephone system, an exchange, a subscriber's line terminating thereat, automatic and manual connecting link circuits at said exchange for extending a call from said line, a station for said line having a resistance, a key and switch hook thereat, said resistance being normally short-circuited by said key, and a pair of relays at the central office, one of said relays operating when said switch-hook is operated to extend the line to one of said connecting link circuits and both said relays operating when said key and said switchhook are operated to extend the line to the other of said connecting circuits one of said relays being marginal and inoperative when said resistance is included in the line circuit. 142. In a telephone exchange system, a calling subscriber's station, a pair of line conductors extending from said station to an exchange, a manual connecting link circuit at said exchange, an automatic switch, and means controlled from said station over the pair of line conductors in series for selectively extending the calling station to said manual link circuit or said automatic switch. 143. In a telephone system, a trunk line having two branches at one end, a selector switch, a set of bank contacts in said selector connected to the said trunk line at the end opposite said branches, means whereby said selector is controlled over calling lines to extend connections to said trunk line by way of said contact set, and means automatically responsive whenever a connection is made with the trunk for determining over which branch the call will be routed away from the trunk. 144. In an automatic switch, two sets of wipers, a wiper selecting relay, stepping mechanism responsive to impulses delivered to said switch to advance both sets of wipers simultaneously, and a circuit for said relay closed by one of said wipers when advanced from normal position. 145. In a telephone system, a calling line, an automatic switch, two sets of wipers for said switch, one of said sets of wipers arranged for normal connective use in said switch and the other of said sets arranged for alternative connective use in said switch, a wiper selecting relay for excluding one said set of wipers and for thereupon including the other set therefor, automatic stepping mechanism responsive to impulses delivered to said switch over the calling line for advancing both sets of wipers simultaneously, and a circuit for operating said relay which is closed over said one set of wipers. 146. In a telephone system, a calling line, an automatic switch, two sets of wipers for said switch, one of said sets of wipers arranged for normal connective use in said switch and the other of said sets arranged for alternative connective use in said switch, a wiper selecting relay

for excluding one said set of wipers and for thereupon including the other set therefor, automatic stepping mechanism for advancing both sets of wipers simultaneously, and a circuit for operating said relay which is closed over said one set of wipers.

147. In a telephone system, a calling line, an automatic switch, two sets of wipers for said switch, one of said sets of wipers arranged for normal connective use in said switch and the other of said sets arranged for alternative connective use in said switch, a wiper selecting relay for excluding one said set of wipers and for thereupon including the other set therefor, automatic stepping mechanism for advancing both sets of wipers simultaneously, a called line cooperative with each of said sets of wipers, respectively, means for connecting the calling line by said one set of wipers to its corresponding said called line, means controlled over a conductor of the said connected called line and one of the wipers of said connection for operating the selecting relay, and means for thereafter operating the sets of wipers simultaneously to cause the calling line to be connected through said other set of wipers to its corresponding called line.

148. In a telephone system, a calling line, an automatic switch, two sets of wipers for said switch, one of said sets of wipers arranged for normal connective use in said switch and the other of said sets arranged for alternative connective use in said switch, a wiper selecting relay for excluding one said set of wipers and for thereupon including the other set therefor, automatic stepping mechanism responsive to impulses delivered to said switch over the calling line for advancing both sets of wipers simultaneously, a called line cooperative with each of said sets of wipers, respectively, means for connecting the calling line by one set of wipers to its corresponding said called line, and means controlled from the calling line over a conductor of the said connected called line and one of the wipers of said connection for operating the selecting relay, and means for thereafter operating the sets of wipers simultaneously to cause the calling line to be connected through said other set of wipers to its corresponding called line.

149. In a telephone system, a calling line having an automatic switch associated therewith having access to a plurality of large groups of lines, each group being further divided into sub-groups, said switch having motion in one plane to elect one of said sub-groups and in another plane to select a line in the elected sub-groups, and means associated with the switch and automatically operated for electing a group of said lines, said group electing means operable either before the switch is moved or after it has moved in one plane.

150. In a telephone switch, a subscriber's line, a series of switches comprising group selectors, hundreds selectors, and connectors directly controlled by the subscriber on said line for connecting with a second line, a second series of switches comprising group selectors, thousands selectors, hundreds selectors, and connectors similarly controlled for connecting with a third line, and automatic telephone numbers assigned to said lines all having the same number of digits.

151. In a telephone system, a subscriber's line, a first selector, means including said first selector, a second selector, and a connector directly controllable by the subscriber on said line

for connecting with a second line, means including said first selector, another second selector, a third selector, and another connector similarly controlled for connecting with a third line, telephone numbers for said second and third lines having the same number of digits, and means for automatically releasing said first selector whenever the said second line is called in order to cancel one of the digits in the number.

152. In a telephone system, means including a plurality of serially related directly controlled automatic switches for connecting a calling and a called subscriber's line, a different and lesser plurality of similar switches for connecting the said calling line with another called line, a uniform numbering system in which all the said subscribers have the same number of digits in their telephone numbers, and means for releasing one of the switches used in calling the said second called line when such switch is first operated in order to cancel one of the digits in the number.

153. In a telephone system, a selector switch and means for operating the same, said switch having a primary movement and an automatic secondary selecting movement, a slow acting relay energized during the primary movement and deenergized on the completion thereof to start the secondary movement, a release magnet, and a circuit for said magnet closed by said relay upon deenergizing in case the primary movement has stopped at a certain predetermined point.

154. In a telephone system, a first line, a second line, means including a plurality of serially related directly controlled automatic switches for setting up a connection from said second line to said first line, means including a different number of similar switches for setting up a connection from said first line to said second line, and means for operating said switches according to a uniform numbering arrangement such that said first line and said second line are both called by means of the same number of digits.

155. In a telephone system, a first line, a second line, means including a plurality of serially related directly controlled automatic switches for setting up a connection from any calling line to said first line, means including a smaller number of similar switches for setting up a connection from any calling line to said second line, and means for operating said switches according to a uniform numbering arrangement such that said first line and said second line are both called by means of the same number of digits.

156. In a telephone system, a first line, a second line, means including a plurality of serially related directly controlled automatic trunk selecting switches for setting up a connection from said second line to said first line, means including a different number of similar switches for setting up a connection from said first line to said second line, and means for operating said switches according to a uniform numbering arrangement such that said first line and said second line are both called by means of the same number of digits.

157. In a telephone system, a connector switch and a line accessible thereto, another similar connector and a second line accessible thereto, means including a plurality of serially related directly controlled automatic trunk selecting switches for setting up a connection from any calling line to said first line by way of the first mentioned connector, means including a differ-

- ent number of similar switches for setting up a connection from any calling line to said second line by way of the second mentioned connector, and means for operating said switches according to a uniform numbering arrangement such that said first line and said second line are both called by means of the same number of digits.
163. In a telephone system, a plurality of lines, a plurality of other lines, means including a plurality of serially related directly controlled automatic switches for setting up a connection from any calling line in either of said pluralities to any line of the first mentioned plurality of lines, means including a smaller number of similar switches for setting up a connection from any calling line to either of said pluralities to any line of said plurality of other lines, and means for operating said switches according to a uniform numbering system such that both called lines are called by means of the same number of digits.
164. In a telephone system, two exchanges, means including a plurality of serially related directly controlled automatic switches for connecting a calling line in either exchange with a called line in the first exchange, means including a smaller number of similar switches for connecting a calling line in either exchange with a called line in the second exchange, and means for operating said switches according to a uniform numbering arrangement such that the lines in one exchange are called by means of the same number of digits as the lines in the other exchange.
165. In a telephone system, a subscriber's line, a first selector, means including said first selector, a second selector, and a connector directly controllable by the subscriber on said line for connecting with a second line, means including said first selector, another second selector, a third selector, and another connector similarly controlled for connecting with a third line, telephone numbers for said second and third lines having the same number of digits, and means in said first selector for automatically canceling one of the digits in the number whenever said second line is called.
166. In a telephone system, means including a plurality of serially related directly controlled automatic switches for connecting a calling and a called subscriber's line, a different and lesser plurality of similar switches for connecting the said calling line with another called line, a uniform numbering system in which all of the said subscribers have the same number of digits in their telephone numbers, and means in one of the switches used in calling the said second called line for canceling one of the digits in the number thereof.
167. In a telephone system, a selector switch and means for operating the same, said switch having a directive primary movement and an automatic secondary selecting movement, means normally effective to start the secondary movement at the end of the primary movement, a release magnet, and a mechanically adjustable contact device operated responsive to the primary movement but effective only at the end thereof for closing a circuit for said release magnet in case the primary movement has stopped at a predetermined point, whereby said switch can be caused to restore at the end of the primary movement of any desired extent.
168. In a telephone system, a calling line, an automatic selective switch, groups of lines accessible from said switch, a wiper of said switch, a motor magnet of said switch, a line relay of said switch, means for transmitting series of impulses over said line for operating the relay, means responsive to the operation of the relay to correspondingly operate the motor magnet to in turn correspondingly move the wiper from normal resting position to thereby select the desired said group of lines by the wiper, and means whereby the relay will operate responsive to a predetermined number of said series before a said series will cause the operation of the motor magnet.
169. In an automatic telephone system, a calling line, an automatic selective switch, a wiper of the switch, levels of lines accessible from said wiper, each level reached by a specific different selective movement of the wiper, and the lines of the level selected then selected by a selective movement of the wiper along the latter said level, a motor magnet of said switch, a line relay of said switch, means for transmitting a train of series of impulses over said line for operating the relay, means responsive to the operation of the relay to correspondingly operate the motor magnet to correspondingly operate the wiper to thereby select a desired said level and a line of the level selected responsive to selecting the level, and means whereby the relay will operate responsive to a predetermined number of said series before a said series will cause the operation of the motor magnet.
170. In an automatic telephone system, a calling line, an automatic selective switch, groups of lines accessible from said switch, a wiper of said switch, a motor magnet of said switch, a line relay of said switch, means for operating the motor magnet from normal resting position responsive to the relay to move the wiper to select a desired one of said groups of lines corresponding to the extent of operation of the motor magnet, means for transmitting a train of series of impulses over said line for operating the relay, and means for absorbing a predetermined number of said series of the train sent effective to operating said relay but non-effective to said motor magnet before the next succeeding series of the train will be rendered effective to operate said motor magnet.
171. In an automatic telephone system, a calling line, an automatic selective switch, a shaft and wiper thereon of the switch, a relay individual to the shaft, groups of lines accessible from said wiper, a called telephone number reached over a random line of a said group, means for operating the motor magnet responsive to the relay to move the wiper from normal resting position to select last said group of lines, the wiper moving corresponding to the extent of operation of the motor magnet and the particular group selected, means for sending a train of series of impulses over the calling line corresponding to the digits and numerical order thereof in the telephone number, and means for operating the motor magnet responsive to only a particular one numerical order series of the train of impulse series, although a plurality of series of impulses of the train corresponding to a plurality of digits of the telephone number antecedent to the said particular series are sent effective to the relay.
172. In an automatic telephone system, a calling line, an automatic selective switch, a shaft and wiper thereon of the switch, a relay individual to the shaft, groups of lines accessible from said wiper, a called telephone number reached over a random line of a said group, means for operating the motor magnet responsive to the relay to move

- the wiper from normal resting position to select last said group of lines, the wiper moving corresponding to the extent of operation of the motor magnet and the particular group selected, means for sending a train of series of impulses over the calling line corresponding to the digits and numerical order thereof in the telephone number, and means for operating the motor magnet responsive to only a particular one numerical order 5 of the train of impulse series, although a series of impulses of the train corresponding to a digit of the telephone number antecedent to said particular series is sent effective to the relay. 1080
168. In an automatic telephone system, a calling line, a selective switch, means for extending the calling line to the selective switch, levels of bank line terminals of the switch, a wiper of said switch, a stepping magnet of said switch for stepping the wiper into selective alignment with 15 a desired said level, a line relay of the switch correspondingly operated in accordance with successive series of a train of series sent over the calling line, means for absorbing the first series of impulses of the train sent to the switch although the line relay will operate in correspondence with and in accordance with the series absorbed without operating the stepping magnet, and means for causing the stepping magnet to 20 first operate responsive to the next succeeding 85 series in the train. 105
169. In an automatic telephone system, a calling line, a selective switch, means for extending the calling line to the selective switch, levels of bank line terminals of the switch, a wiper of 30 said switch, a stepping magnet of said switch for stepping the wiper into selective alignment with a desired said level, a line relay of the switch correspondingly operated in accordance with successive series of a train of series sent over the 35 calling line, means for absorbing a successive plurality of the first series of the train of impulses sent to the switch although the line relay will operate in correspondence with and in accordance with the series absorbed without operating the 40 stepping magnet, and means for causing the stepping magnet to first operate responsive to the next succeeding series following the last of 110 said plurality of said series. 115
170. In an automatic telephone system, a calling line, an impulse series sender on the calling line for sending a train of impulse series, a trunk line, a selective switch terminating the trunk line, a wiper of the switch, levels of bank terminals of the switch accessible from the wiper, 50 a motor magnet of the switch for operating the wiper from normal resting position into alignment with a desired said level, means for extending connection from the calling line to the trunk line, means responsive to thereafter sending a 55 series of impulses from said sender for correspondingly operating the wiper to thereby align the wiper with the one of said levels corresponding to the number of impulses in the series sent, and means whereby a said series of said train 60 must be sent to the trunk to prepare for rendering the motor magnet first operative to operate the wiper into alignment with a said level responsive to the next succeeding series of a train of 65 series sent to the trunk line. 130
171. In an automatic telephone system, a calling line, an impulse series sender on the calling line for sending a train of impulse series, a trunk line, a selective switch terminating the trunk line, a wiper of the switch, levels of bank terminals of the switch accessible from the wiper, 70 a motor magnet of the switch for operating the wiper from normal resting position into alignment with a desired said level, means for extending connection from the calling line to the trunk line, means responsive to thereafter sending a series of impulses from said sender for correspondingly operating the wiper to thereby align the wiper with the one of said levels corresponding to the number of impulses in the series sent, and means whereby a said series of said train 75 must be sent to the trunk to prepare for rendering the motor magnet first operative to operate the wiper into alignment with a said level responsive to the next succeeding series of a train of series sent to the trunk line. 140
172. In an automatic telephone system, a selective switch, a wiper of the switch, a magnet of the switch for moving the wiper to select a group of accessible lines, a relay of the switch for operating the magnet, a calling line terminating in the switch, means for sending a train of series of impulses over the calling line for operating the relay, and means whereby only after the last impulse of a series of impulses has been sent effective to the relay will the magnet become operative responsive to the relay and then only when the next succeeding series of the train is sent will the magnet first operate, the wiper being in its normal resting position as when the switch is idle at the time the first operation of the magnet occurs. 100
173. In an automatic telephone system, a selective switch, a wiper of the switch, a magnet of the switch for moving the wiper to select a group of accessible lines, a relay of the switch for operating the magnet, a calling line terminating in the switch, means for sending a train of series of impulses over the calling line for operating the relay, and means whereby only after the relay has absorbed one of said impulse series non-effective to the magnet will the relay be prepared to first 115 operate the magnet to move the wiper from its normal resting position as when idle. 113
174. In a telephone system having a uniform numbering system in which all of the subscribers have the same number of digits in their telephone numbers, means including a first selector for directly connecting a calling and a called subscriber's line, said first selector having wipers and a plurality of bank levels accessible from 120 said wipers, means whereby the first digit of certain telephone numbers will determine what particular level of the first selector will be used in completing the connection to the line indexed by the number called, means whereby the first digit of other certain telephone numbers will only determine a plurality of said levels an unknown one of which will be used in completing the connection to the line indexed by the number called, and means whereby the second digit of 125 said other certain telephone numbers will determine which particular one of the levels of said plurality last determined will be used in completing the connection to the line indexed by the number called. 130
175. In a telephone system having a uniform numbering system in which all of the subscribers have the same number of digits in their telephone numbers, means including a first selector and a plurality of serially related directly controlled 135 automatic switches for connecting a calling and a called subscriber's line, said first selector having wipers and a plurality of bank trunk levels accessible from said wipers, means whereby the first digit of certain telephone numbers will determine what particular level of the first selector 140
176. In a telephone system having a uniform numbering system in which all of the subscribers have the same number of digits in their telephone numbers, means including a first selector and a plurality of serially related directly controlled 145 automatic switches for connecting a calling and a called subscriber's line, said first selector having wipers and a plurality of bank trunk levels accessible from said wipers, means whereby the first digit of certain telephone numbers will determine what particular level of the first selector 150

- will contain the trunk to be used in completing the connection to the line indexed by the number called, means whereby the first digit of other certain telephone numbers will only determine a plurality of said levels an unknown one of which will contain the trunk to be used in completing the connection to the line indexed by the number called, and means whereby the second digit of said other certain telephone numbers will determine which particular one of the levels of said plurality last determined will contain the trunk to be used in completing the connection to the line indexed by the number called. 80
176. In a telephone system, an automatic switch, a plurality of terminals, automatic switching mechanisms for seizing any desired one of said terminals, and means responsive to such seizure for operating the wipers of said switch in accordance with the terminal seized. 85
177. In a telephone system, an automatic switch directly controlled to pick out a group of lines, a trunk line leading to said switch having a plurality of branches, an automatic switch for seizing said trunk by way of any one of said branches, and automatic means responsive to said seizure for automatically operating said switch to pick out the particular group of lines corresponding to the branch over which the trunk line is seized. 90
178. In a telephone system, an automatic switch directly controlled to pick out a group of lines, a trunk line leading to said switch having a plurality of branches, automatic switching mechanism for seizing said trunk line via one branch, automatic means responsive to said seizure for automatically operating said switch to pick out a particular group of lines, said last means responsive to the seizure of said trunk via another branch to operate said switch to pick out a different group of lines. 105
179. In a telephone system, a trunk line having a plurality of branches at one end thereof, an automatic switch at the other end of said trunk line, other trunk lines accessible to said switch and arranged in groups, said groups corresponding, respectively, to said branches, a switch controller associated with said first trunk line, automatic switching mechanism for connecting with said first trunk line via any one of said branches, and means responsive to the completion of the connection for automatically operating said controller to cause said switch to select an idle trunk line in the particular one of said groups which corresponds to the branch in use. 110
180. In an automatic telephone system, a selective switch, means for operating said switch from its normal resting position, means for restoring the operated switch back to its normal resting position, means for connecting to said switch, means involving a predetermined potential on a certain conductor of said switch for barring connection to the switch, means operated responsive to the removal of said potential for causing said switch to be restored to its normal resting position, and means for applying said predetermined potential to said conductor for preventing the switch from being connected to while the switch is in the act of restoring and for thereupon unbarring it. 115
181. In an automatic telephone system, a selective switch, means for operating said switch from its normal resting position, means for restoring the operated switch back to its normal resting position, means for connecting to said switch, means involving a predetermined potential on a certain conductor of said switch for barring connection to the switch, means operated responsive to control over said conductor for causing said switch to be restored to its normal resting position, and means for applying said predetermined potential to said conductor for preventing the switch from being connected to while the switch is in the act of restoring and for thereupon unbarring it. 120
182. In an automatic telephone system, a first selective switch having leading-in talking conductors and a release trunk conductor, a second switch for effecting connection to said first switch over all said conductors, means for barring said connection to said first switch by the presence of predetermined potential on said release trunk conductor, means for directly operating said second switch into connection with said first switch and for then operating said first switch to further extend the connection, a restoring magnet for said first switch, means responsive to removing said potential for causing said second switch to restore from its connection and for causing the effective operation of said magnet to restore the operated state of said first switch to the condition existing before said second switch connected to it, and means also operated immediately following the removal of said potential and responsive thereto and after the magnet has effectively energized for applying said potential to the release trunk conductor until said first switch has been restored and thereupon removing it so that the said first switch will be barred against connection with while in the act of restoring and thereupon unbarred. 125
